ASSEMBLING AND PACKAGING OF SHEET MATERIAL

Edwin K. Smith, Jr., Haworth, N.J., Robert Foster, Forest Hills, N.Y., and Clinton F. Brundage, Mahwah, and Nelson D. Tremaine, Glen Rock, N.J., assignors to McCall Corporation, Dayton, Ohio, a corporation of Delaware

Filed June 19, 1963, Ser. No. 288,978
18 Claims. (Cl. 53—54)

This invention relates to apparatus for assembling and packaging a plurality of sheets of thin paper or the like, and is particularly concerned with the assembling and packaging of the several printed sheets of tissue paper which comprise a dress-making pattern or the like.

One of the principal objects of the present invention is to provide an automatic pattern assembling, folding and packaging machine which is capable of relatively high speed operation, and which can perform a function which is at the present performed almost exclusively by manual labor. While it will be obvious from the description of the machine that its principle of operation can be applied to analogous fields, and therefore the invention should not be considered as confined to the packaging of dress-making patterns, nevertheless the utility of the present invention is of particular importance in the art of assembling, folding and packaging dress-making patterns.

These patterns are comprised of several sheets of thin, rather flimsy tissue paper or the like on which the outline of the various parts or panels of a pattern are printed, sometimes along with appropriate instructions. Depending upon the size and complexity of the piece of wearing apparel which is to be made from the pattern, there may be more or less parts, panels, or sections, printed on the pattern sheets. There may be a greater or lesser number of such sheets, and the sheets may vary in size, and sometimes in shape.

The assembling, packaging and folding operations are presently performed manually by persons who take a bundle of each of the sheets making up the specified pattern, for example in a given size or size range, mount these sheets on a rack in bundles of the different sheets which comprise the pattern, and then withdraw a sheet from each bundle, with the largest sheet preferably being arranged so as to enfold any smaller sheets. Then the pattern folder performs the folding operation on the assembled pattern sheets to reduce them to a specified size and inserts them in a package such as a paper envelope, often along with a separate printed instruction sheet. In establishments where large numbers of patterns are manufactured, and it should be recalled that for each design of pattern there may be a number of different actual patterns due to the variance in the size ranges, a substantial amount of manual labor is required for the pattern assembling and packaging operation. Obviously, in order to keep up with the rate of production of modern printing equipment it is necessary to employ sufficient persons to assemble, fold and package the patterns at a corresponding rate. This may mean for example the employment of several hundred persons whose sole function is to perform this operation.

Accordingly, the principal object of this invention as mentioned above is to provide a novel machine which is capable of assembling, folding and packaging the various sheets making up a pattern or the like, at rates which are comparable to the rate of production of equipment on which the patterns are printed, thereby obtaining uniformity of the end product package and thereby reducing the expense of this operation which heretofore has been performed by manual labor.

Another object of the invention is to provide such a

2

pattern folding machine which is capable of sensing the existence of an incomplete assembly of sheets making up a given pattern, and of rejecting such incomplete pattern to separate it from those patterns which are complete and salable.

Another object of the invention is to provide such a pattern folding machine which is capable of a relatively wide range of assembling operations, and may therefore be preset to operate on the assembling, folding and packaging of different types of patterns which are made up of substantially different numbers of sheets.

An additional object of the invention is to provide in such a pattern folding machine a novel control which causes the machine to reject those incomplete patterns which may result during a starting and stopping of a cycle of operation for the packaging of a specified pattern.

A further object of the invention is to provide such a machine which is capable of performing the assembling operation without damaging the relatively thin paper of the individual sheets.

Another object of the invention is to provide such a pattern folding machine which includes aids to its operators enabling them to set up the machine for a particular assembling and folding operation with relative ease.

Another object of the invention is to provide such a pattern folding machine wherein the bundles of the several sheets comprising a specified pattern can be set up on the machine while the machine is operating and assembling, folding and packaging different patterns.

An additional object of the invention is to provide a novel pickup mechanism for the feeding of paper sheets and the like, whereby it is possible to remove sheets one at a time from a pile thereof without advancing the pile toward the feeding mechanism, and to deliver the sheets at a position which remains fixed with reference to the feeding mechanism.

A further object of the invention is to provide such a sheet feeding mechanism which is capable of engaging the top sheet of a pile draped over a supporting rod or the like at some point between the ends of the sheet, whereby the sheet is folded up during the pickup operation and is delivered in a folded condition whereby its length is substantially reduced from its actual length.

A further object of the invention is to provide a novel assembling apparatus in which a plurality of different sheets are grouped at relatively high speeds on a continuously moving conveyor or the like, and from which the groups of sheets can readily be removed for further handling as a group.

An additional object of the invention is to provide a novel stream-folding mechanism for sheet material, including selectively movable foldable plows which function to accelerate the folding operation of sheets conveyed past the plows, thus effectively reducing the length of the stream-folding apparatus and its associated conveyor or conveyors.

Other objects and advantages of the invention will be apparent from the following description, the accompanying drawings and the appended claims.

60 In the drawings:

FIG. 1 is a side elevational view of the assembling and stream-folding mechanisms of a pattern folding machine incorporating the invention;

FIG. 2 is a side elevational view, on a slightly smaller scale, showing the overall arrangement of the tuck folding and packaging mechanisms of the machine;

FIG. 3 is a perspective diagrammatic illustration of the assembling, folding and packaging process as performed by a machine according to the invention;

70 FIG. 4 is an enlarged elevational view, with some parts broken away and shown in section, illustrating the construction of the drive mechanism of the machine, the

general area of this view being shown by the line 4—4 on FIG. 1;

FIG. 5 is a sectional view on an enlarged scale taken through one of the drive gear units shown in FIG. 4;

FIG. 6 is a detail view on an enlarged scale showing the unit which controls the acceleration and deceleration of the line shafts of the machine whereby a non-uniform rotation thereof is obtained;

FIG. 7 is a sectional view, on an enlarged scale, taken through the assembling mechanism of the machine generally on the line 7—7 indicated on FIG. 1;

FIG. 8 is an enlarged detail view showing one of the sheet carrying bars on the assembling conveyor;

FIG. 9 is an enlarged detail view showing a portion of the pneumatic-electric control and detector mechanisms, of which there is one at each of the stages of the assembling mechanism, and the location of one of which is shown in FIG. 7;

FIG. 10 is a sectional view on an enlarged scale, with some parts broken to reduce the size of the view and other parts broken away and shown in section, illustrating the general construction of one of the sheet pickup devices of the assembling mechanism, together with its associated power take off from a line shaft and its associated vacuum supply;

FIG. 11 is an enlarged detail section showing a portion of the mounting of the pickup device;

FIG. 12 is an enlarged detail section, with the vacuum supply shown in elevation, and with certain parts broken away, showing the arrangement of vacuum conduits in one of the sheet pickup devices;

FIG. 13 is an enlarged detail section taken on line 13—13 in FIG. 10;

FIG. 14 is an enlarged detail section taken on line 14—14 in FIG. 10;

FIG. 15 is an enlarged detail view of one of the vacuum pickup fingers which are a part of each sheet pickup cylinder, particularly as shown in FIGS. 10 and 13;

FIG. 16 is a detail view of one of the latching control mechanisms for the pickup device;

FIG. 17 is a view of one of the bundle support saddle mechanisms, as seen looking through a section of the assembling mechanism, approximately beneath one of the sheet pickup devices, and with a portion of such device illustrated schematically above that saddle bar appearing to the right of FIG. 17;

FIG. 18 is a somewhat diagrammatic sectional view, taken generally along the lines 18—18 of FIG. 17 and showing the relationship of the saddle bar with respect to the pickup mechanism, this relationship also appears on FIG. 13 on a larger scale;

FIG. 19 is a detailed view of one of the cam follower control mechanisms on one of the pickup devices, portions of such mechanism also being shown in dotted lines on FIG. 13;

FIG. 20 is an enlarged elevational detail view, looking down upon two successive sheet pickup cylinders, and showing the relationship of these cylinders with respect to the guide plates or bars which cooperate with the assembling conveyor in transferring a sheet from the cylinders to such conveyor;

FIG. 21 is an enlarged detailed view illustrating the cooperation of the assembling conveyor at its discharge end of the grippers on the stream-folding conveyor which pick up the assembled sets or groups from the assembling conveyor;

FIG. 22 is a sectional view taken on line 22—22 of FIG. 1, and showing on a larger scale the general arrangement of the discharge from the assembling conveyor;

FIG. 23 is an enlarged detail view showing the operation of the stream-folding conveyor grippers, illustrating the open position of one gripper in dotted lines;

FIG. 24 is a plan detail view of one of such grippers on approximately the same scale as FIG. 23;

FIG. 25 is a plan view, with some parts broken away, of the stream-folding mechanism;

FIGS. 26 and 27 are diagrams illustrating a typical sequence of the stream-folding operations, with the group of sheets treated as a unit and illustrated by a single line;

FIG. 28 is a perspective detail view of the stationary and movable folding plows of the stream-folding apparatus;

FIG. 29 is a diagrammatic view showing the general operation of the movable folding plows;

FIG. 30 is a side elevation view of the folding portion of the machine, as shown generally in FIG. 2, but on a substantially larger scale, and illustrating the manner in which this folding mechanism discharges into the reject mechanism and the instruction sheet inserter;

FIG. 31 is a detailed view, on a larger scale, showing the reject mechanism for segregating incomplete patterns from the complete and acceptable patterns prior to the instruction sheet insertion;

FIG. 32 is a somewhat schematic drawing of the drive for the folding apparatus shown in FIG. 30, the view being taken from the same direction, but with all rollers, belts, plates, etc., removed;

FIG. 33 is a side elevational view on an enlarged scale showing details of the guide sheet inserter and the packaging mechanism;

FIG. 34 is a view similar to FIG. 32, showing the drive for the guide sheet inserter and the packaging mechanism, as continued from FIG. 32;

FIG. 35 is a side view of the guide sheet inserter mechanism, as viewed at right angles with respect to FIG. 33;

FIG. 36 is a plan view of the conveyor parts of the guide sheet inserter mechanism;

FIG. 37 is a detail view on a substantially enlarged scale showing the mechanism for feeding the packaging envelopes;

FIG. 38 is a view similar to FIG. 37, showing an envelope about to be withdrawn from the hopper;

FIG. 39 is an end view of the memory and control mechanism which is located at the head end of the machine as shown in FIG. 1;

FIG. 40 is a detail view on an enlarged scale, looking from the left of FIG. 39, and with portions broken away to show details of the controls;

FIG. 40A is a detail sectional view on an enlarged scale showing a segment of the memory device, and taken on line 40A—40A of FIG. 40;

FIGS. 41A, 41B, 41C, 41D and 41E, taken together, comprise the schematic electrical diagram of the control circuits of the machine; and

FIG. 42 is a schematic diagram showing the relationship of the timing and control cams which appear in the various sections of the circuit diagram.

Referring to the drawings, which illustrate a preferred form of the invention, it will be seen that the apparatus is comprised of several serially connected and commonly driven mechanisms as follows:

(A) The assembling apparatus, which includes a plurality of sheet bundle-supporting saddles and a sheet pickup mechanism cooperating with each saddle to remove a single sheet from the bundle, together with an assembling conveyor and appropriate transfer devices for removing a sheet from each pickup device which presents a sheet to the conveyor, thereby arranging a sheet from each bundle in groups on the assembling conveyor to form a grouped or completed pattern; there may be any number of such saddles and pickup mechanisms, and in the illustrated device, as shown particularly in FIG. 1, there are preferably twenty pickup stations, although not all of these stations have been illustrated since they are duplicates.

(B) Receiving the grouped patterns from the assembling conveyor is the folding mechanism which is shown in FIGS. 1, 2 and 30, and which accepts the completed

grouping of pattern sheets and folds this group to predetermined dimensions; the folding mechanism then discharges the folded group under control of a transfer conveyor which maintains the folded condition of the group.

(C) Downstream from the folding mechanism and receiving the folded pattern groups therefrom is the reject mechanism shown in FIGS. 2, 13 and 30, which functions to segregate and remove from the machine those patterns which are incomplete by reason of one or more of the sheets thereof not having been included during the assembling operation.

(D) Receiving the acceptable folded patterns after the reject mechanism is the instruction sheet inserter, which senses the passage of an acceptable folded pattern therethrough and operates to add to the pattern the printed instruction sheet explaining the use of the pattern; the inserter mechanism is illustrated particularly in FIGS. 33, 35 and 36.

(E) At the discharge of the machine arranged to accept the completed folded patterns and instruction sheets therewith, is the packaging or stuffing mechanism; the relationship of this mechanism to the previously described sections of the machine is shown in FIG. 2, and details of the stuffing mechanism are shown in FIGS. 33, 37 and 38. In a preferred form of the machine this mechanism includes a hopper containing a supply of empty packaging envelopes, together with devices for removing the envelopes from the hopper one at a time, opening the mouth of the envelope, and guiding the folded pattern and accompanying instruction sheet into the envelope, after which the packaged pattern is discharged from the machine.

(F) All of the above-described mechanisms which form successive and cooperating parts of the machine are driven from a common power source and having coordinated control; this includes lineshafts which provide power and appropriate acceleration and deceleration to the various parts of the assembling mechanism, and continuously operating power drives to the subsequent mechanisms of the machine. The controls coordinate the operation of the various mechanisms, including particularly the reject mechanism, and assure that only complete folded patterns are passed to the inserter mechanism and thence packaged. The controls also provide for flexibility of operation of the assembling mechanism, whereby it is capable of handling patterns which involve different numbers of sheets, up to the maximum station capacity of the assembling mechanism, which in the present case is twenty different sheets.

Overall operation and drive

Referring to FIG. 3, the method of operation followed by the machine is illustrated diagrammatically, using the path of motion of one sheet of a pattern for purposes of description. Thus, the sheet is withdrawn from a bundle of like sheets 50 which are draped over the saddle bars or supports 52. Over the saddle support there is mounted a rotary sheet pickup mechanism shown diagrammatically as the cylinder 54 having one or more vacuum pickup members 55 thereon. These members remove a single sheet, as shown in dotted lines, from the bundle 50 and carry it upward and over the top of the pickup mechanism 54 where the sheet is transferred to a pin bar 60 having a plurality of depending carrier pins 62. This bar is one of a number of like bars comprising part of the assembling conveyor, as will be described.

The sheet, along with other sheets which may be subsequently (or previously) similarly transferred to the pin bar 60, will be carried as a group to the stream-folding mechanism, where the gripper 65 of the stream-folding conveyor will pick up the group of sheets and carry it through the stream-folding operation which is shown schematically at 68. This operation will cause the sides of the grouped pattern sheets to be folded over such that the lowermost sheet encompasses the sheets upon it, and acts effectively as an outer cover. It is for this rea-

son that the largest sheet of the pattern preferably is assembled last, such that its area is sufficient to enfold all of the other sheets. There may be a requirement for more than two side folding operations, as shown, but in any event the sides of the assembled sheets are folded over until the folded pattern reaches a predetermined width, corresponding to the desired width for packaging, i.e., sufficiently smaller than the mouth of the envelope.

The side folded pattern then enters the tuck folding mechanism 70, where it may be folded upon its length a number of times, usually twice, and the pattern, then completely folded, passes to the inserter mechanism where the instruction sheet 72 is added to the folded pattern. This may be accomplished by placing the instruction sheet in the conveyor mechanism and causing the folded pattern to rest upon the sheet as shown. The assembled instruction sheet and pattern is then inserted in an open mouthed paper envelope 75, or some equivalent package or wrapper, and the completed packages are discharged as shown.

The power for the entire apparatus is provided by a motor 90 (FIG. 4) driving a pulley 92 which is in turn connected through a belt, chain, or the like 93, to a further pulley 94 fastened on a countershaft 95. This shaft is mounted crosswise of the head or starting end of the machine, shown at the left end of FIG. 1. The countershaft extends into two identical timing control mechanisms 100a and 100b, which are of the same internal construction, and which differ only in the time phase relation of their outputs. Details of such mechanisms are shown in FIGS. 5 and 6.

The countershaft also provides a power take-off drive 101 to a lubricant pump 102, connected as shown schematically by dot-dash lines to circulate lubricating oil through the two mechanisms 100a and 100b. There is a further power take-off drive 104 connected to drive a lineshaft 105 which extends the full length of the assembling mechanism of the machine, as shown in FIG. 1. This shaft is mounted for rotation in a series of bearing blocks 107, and is driven through a right angle gear drive 108 from the power take-off 104.

It will be seen accordingly that the drive mechanism is mounted at the head end of the machine, and that the assembling mechanism, indicated in FIG. 1 by the general reference numeral 120, has the lineshaft 105 extending its full length.

On opposite sides of this assembling mechanism there are control and drive shafts 125a and 125b, and 127a and 127b, respectively (see FIGS. 1, 4, 7 and 10), and it will be understood that there are such shafts on each side of the assembling mechanism, driven respectively from the mechanisms 100a and 100b. The shafts 125 rotate at a constant angular velocity, and receive their input from a worm gear 126 (FIG. 4) in the control mechanism 100a or 100b. Only the internal structure of mechanism 100a is exposed and explained in detail, since these mechanisms are the same. The worm gear is in turn driven by a worm 128 fixed to the countershaft 95.

Referring to FIG. 5, an input gear 130 is also driven along with worm gear 126, for example by having the two gears splined or keyed to shaft 125. Input gear 130 meshes with a larger gear 132 fastened to a small countershaft 133 within the mechanism, and this shaft is in turn mounted for rotation within the bearings 134 held in the housing of the mechanism 100a. One end of countershaft 133 extends forwardly beyond the corresponding support bearing, and fastened to the extending end of this shaft, as through a drive key (not shown) is a constantly rotating input drive arm 135.

As shown in FIG. 6, arm 135 has a pivot connection, as through a pin 137, to a cam follower arm 138, and this arm in turn has a roller cam follower 140 fitted within the cam track 142. This track is formed in plate 143 suitably fastened to the housing of the mechanism,

and thus as arm 135 rotates the roller 140 follows the cam track producing a motion of arm 138 which is in effect an accelerating and decelerating rotary movement with respect to the pivot pin 137. An output arm 145 is connected through a separated pivot pin 146 to the outer end of arm 138, and the other end of arm 145 has a pivoting drive connection 148 to an output gear 150. It will be noted that some of the arms have been omitted from FIG. 5 for purposes of clarity.

Accordingly, with arm 135 driven in a clockwise direction as shown in FIG. 6, the output gear 150 will likewise rotate in a clockwise direction, but it will have a non-uniform rotation, with alternate periods of accelerating and deceleration. Gear 150 meshes with a further gear 152 fastened to the shaft 127a, and therefore this shaft likewise has a continuous non-uniform rotary movement, with predetermined periods of acceleration and deceleration.

The mechanism 100b is of the same construction and functions in the same manner, except that the cam arrangement is displaced 180° with respect to the cam in the mechanism 100a. Therefore, the shafts 127 (a and b) on opposite sides of the machine each have the same type of accelerating and decelerating rotary movement, but the periods of acceleration and deceleration are 180° out of phase. The purpose of this relationship is explained in connection with the detailed explanation of the assembling mechanism.

Assembling mechanism

The assembling mechanism 120 includes a plurality of pickup stations (for example twenty as mentioned) and each station comprises a supporting or saddle structure adapted to carry a bundle of like sheets forming one part of a pattern. The saddle structure is shown in FIG. 17. It includes a cart-like base frame 160 having a number of supporting wheels 161 which move over tracks 162. There may be one pair of such tracks for several pickup stations. Suitable stanchions or rods 165 extend upwardly from the carriage frame, and cross bars 166 are mounted at the top of these rods, providing in turn a mounting for the support brackets 168 of a pair of saddle bars 52a and 52b. These are the same saddle bars as mentioned previously in connection with FIG. 3, and two bars are provided in aligned relation such that one, bar 52a in FIG. 17, is in an active or working position under the pickup station while the other, 52b, extends to one side of the assembling mechanism and is accessible to the operators of the machine so that they can be placing additional bundles thereon in preparation for the next folding operation while the machine is running.

The bars are provided with sets of color coded reference marks 53, these marks preferably being arranged symmetrically with respect to the indicated center line (C. L.) of the assembling mechanism. Therefore, when the saddle bars are in operative position under the mechanism these marks are arranged symmetrically. The marks are useful in assisting the operator in proper placement of the bundles in a centered or predetermined offset position on one or the other of the bars 52a or 52b. A similar color coding arrangement is carried through the pickup mechanism, as will be described. It will be appreciated that such a centering arrangement is useful since when different patterns are being assembled and folded, the respective sheets thereof may be of different dimensions, and it is desirable to be able to locate the bundles properly with respect to the pickup mechanism since this determines the ultimate position of the picked up sheet or sheets when they are assembled and enter the stream-folding mechanism.

With reference to FIG. 18, an auxiliary support rod or bar 169 is shown extending parallel to and somewhat below the main saddle bar 52a. This auxiliary bar has been found desirable to control the drape of the bundle of sheets on the saddle structure.

Each pickup station has over the saddle bars a pickup

70 75

cylinder 170 (FIG. 10) which is a so-called skeleton cylinder, mounted on and rotatably driven through end supports 172 of Y-shape as shown in FIG. 12. Various details of this cylinder construction are shown in FIGS. 11-15 and 19, and the overall arrangement of the cylinders with respect to each other is apparent from FIG. 1. It will be understood that each of the pickup cylinders and associated mechanisms is duplicated at each pickup station. The only difference between them is that every other pickup cylinder rotates 180° out of phase with respect to the preceding and following pickup cylinders, referring to the flow of material which is from left to right as viewed in FIG. 1.

The pickup cylinders are all driven from one or the other of the shafts 127, and since these shafts rotate with an accelerating and decelerating motion, 180° out of phase, the pickup cylinders driven therefrom will rotate in a like manner. Thus, for purposes of description the pickup cylinders will be referred to as the odd and even numbered cylinders, counting from the left of FIG. 1 where the pickup cylinder in the first position would be number 1. The odd numbered cylinders are driven from shaft 127a, which is on the side of the machine shown in FIG. 1, and the even numbered cylinders are driven from shaft 127b, which appears in FIGS. 4, 7 and 10.

In FIG. 10 one of the even numbered pickup cylinders is shown, and thus the end support 172 is coupled to a drive sleeve or shaft 174 which extends from a right-angle gear drive 175 through which shaft 127b extends. The gear drive obtains its power from this shaft, and in turn drives the cylinder 170.

There are two of the end supports 172, and they are of like construction. The hub part 177 is hollow, providing a passageway 178 (FIG. 12) which extends through one of the arms of the Y-shaped member. A fragment of such arm of the opposite end support member is shown in FIG. 12. The hub portions 177 thus define the axis of rotation of the pickup cylinder 170, and the cylinder structure itself is mounted from these end supports. As shown particularly in FIGS. 11 and 12, there are spaced parallel tubes 180 and 182 which extend into suitable sockets formed in the end supports 172. These tubes are therefore parallel to and offset from the axis of rotation of the pickup cylinder. Tube 180 has its interior communicating with the passageway 178, and that end of the tube 180 which is closest to the gear drive 175 is provided with a plug 183. One or more short nipples 184 extend from the tube 180, to provide a vacuum supply as will be described.

On the opposite or vacuum supply side, a sleeve 185 holds the end support 172. This sleeve and shaft 174 are each mounted in roller bearings 186 (FIGS. 10 and 11) carried in the machine frame structure 188.

Near the opposite ends of the tubes 180 and 182 (FIG. 11) but inward of the openings through the frame brackets 189 are slide blocks 190 which are shown in detail in FIG. 19. These blocks are provided with a central way or slide 192 which extends perpendicular between the tubes 180 and 182. Between these blocks there is a hollow vacuum manifold tube 195 (FIGS. 11, 12 and 13), which has plug members 196 at its opposite ends, and which provide a mounting for the manifold tube in a suitable carrier block 197. The manifold tube also has at least one nipple 198 extending therefrom, and adapted to be connected with a corresponding nipple 184 by a suitable flexible hose, indicated schematically by the dot-dash line 199 in FIG. 12.

A plurality of vacuum pickup members 55 extend outwardly from the manifold 195. Each of these, providing a pickup finger, is a relatively small tubular member, and there are a sufficient number of these pickup fingers spaced apart across the cylinder structure to provide for the handling of different sizes of sheets, i.e., sheets of different widths. As shown in FIG. 15, these fingers preferably are provided with a cap 203 carried on a supporting rod 204 which in turn is mounted in a bracket 205 fastened to one side of the tubular finger. The spring

75

206 is arranged to hold the cap over the end of the finger in the position shown, and if the cap is withdrawn and turned away from the finger, the spring will carry the cap toward the bracket and hence out of the way of the end of the tubular finger. It will be understood that all of the fingers 55, or at least those toward the sides of the pickup cylinder, which may not be used in handling smaller sheets, will be provided with this capping structure. However, to simplify the illustration, this cap structure has been omitted except in FIGS. 13 and 15. 10 The cap is shown in open position in FIG. 13.

The carrier block 197, as previously mentioned, provides a support for the manifold tube 195. Preferably, this includes a subordinate mounting block 208 (FIG. 11) into which the plug 196 is received, and the block 208 includes a pin 209 suitably clamped to the carrier block 197, as shown particularly in FIGS. 11 and 12. The fingers 55 can be color coded in the same fashion as the marks 53 on the saddle bars, providing a quick reference as to which fingers should be uncovered. In this manner the manifold tube is arranged to move with the carrier block, but can readily be removed therefrom for cleaning, repair or replacement, without the necessity of disturbing the control mechanisms for the block. These mechanisms include a control arm 210 (FIGS. 11, 12, 13 and 19) which is rigidly fastened to carrier block 197, and which has a roller follower 212 fastened to its outer end and positioned to ride in a circular track 215 formed in the side frame bracket 189. This track is shown in FIGS. 11 and 12, and also in FIG. 14, wherein it will be apparent that the track has a gap in a lower segment thereof, such gap being indicated generally at 216 in FIG. 14. The roller follower 212 is also shown in that figure, without the arm 210.

The supporting structure for the manifold tube 195, including the slide block 190, is duplicated at opposite ends of the pickup cylinder structure, but the arm 210 is attached only to that carrier block 197 which is opposite from the gear drive unit 175. Thus the drive and manifold control mechanisms will be reversed, side to side, on adjacent pickup cylinders. However, each of the carrier blocks 197 is arranged to move along the slide 192 (FIG. 19), and passes around a locating rod 218 (FIG. 11), which also provides a support for a spring 220. This spring preferably extends partially into the carrier block 197, and acts between such block and a cap 221 fastened to the end of the rod 218. The springs at each end therefore tend to move the manifold tube 195, through its supporting structure, outward from the axis of rotation of the pickup cylinder, and this movement is in turn resisted by contact of the roller 212 with the track 215. During most of the revolutions of the pickup cylinder the manifold tube 195 and the pickup fingers 55 are therefore at a predetermined distance from the axis of rotation of the cylinder, and as shown particularly in FIG. 11, this spacing is sufficient to allow the fingers 55 to clear the top sheet of a bundle 50 supported on a saddle bar therebeneath.

The torsion tube 222 extending around tube 182 is mounted thereon through suitable bearing sleeves 222a (FIG. 12) and carries at its opposite ends fork-like members 223, one of which is shown in FIG. 19. The ends of the fork also appear in FIGS. 11 and 12. These engage blocks 224 which are fitted around a cylindrical portion of the carrier plugs 197, as shown particularly in FIGS. 11 and 19. Thus the torsion tube 222 assures that the radial motion of the plugs 197 at each end of the pickup cylinder is the same and keeps the ends of the pickup fingers 55 in line with each other.

With reference to FIG. 14, a pivotally mounted control arm 225 is fixed to a control shaft 227 extending transversely of the side frame, and offset from the axis of rotation of the associated pickup cylinder. The arm 225 includes an arcuate surface 230 which in one position forms a continuation of the track 215, as shown in 70

full lines in FIG. 14. When the arm 225 is moved away from the track, for example to the position shown in dotted lines, then the roller 212 can drop through the opening 216 and will be controlled by the arm 225, thereby producing a motion of the manifold tube 195 and pickup fingers 55 which is initially outward away from the cylinder axis of rotation, and then back toward such axis as arm 225 returns to its normal position before the roller can reach the point where the track 215 begins. This controlled swinging motion of arm 225 is produced by a control lever 232 fastened to shaft 227 and having a pivotal connection at 233 to a push rod 235. This rod also appears in FIG. 7. A washer 236 fastened to the lower end of rod 235 provides a seat for a drive spring 238, and the upper end of this spring acts against a stationary support bracket 240 which, particularly as shown in FIG. 7, is fastened to a portion of the frame of the machine.

The upper end of rod 235 has a pivotal connection at 20 241 to a rocker arm 242 which in turn has a pivotal mounting on a stub shaft 243 fixed to the machine frame. The rocker arm also has a roller follower 244 which is adapted to engage the pickup control cam 250 fixed to the constantly rotating shaft 125.

25 FIG. 16 shows a latch mechanism for the above-described apparatus, including an arm 252 fastened to the shaft 227. A latch lever 253, having a latching finger 253a at its outer end, is pivotally mounted at 254 on the frame of the machine. The position of the lever 253 is controlled by a solenoid 255 through its armature link 256 connected to the lever 253. Thus, appropriate energizing of solenoid 255 will draw lever 253 downward as shown in FIG. 16 until the finger 253a can engage the arm 252 and lock it against further rotation, thereby 30 holding shaft 227.

35 The spring 238 pushing downward through rod 235 on the arm 232 tends to cause a clockwise motion of the arms 225, 232 and 252 as seen in FIGS. 14 and 16. This motion is prevented by engagement of the roller 244 with cam 250, but in turn when the roller follows the lower portion of the cam, this causes rocking movement of shaft 227 and the arms attached to it. This will not happen, however, if the latch 253 is in the locking position; then the roller 244 will be prevented from following the low 40 portion of cam 250. As a result during rotation of the associated pickup cylinder the roller 212 will follow a completely circular motion about the track 215, and the pickup fingers 55 will not drop to pick up a sheet.

45 If the latch mechanism is deenergized and the pickup 50 mechanism is free to operate, then the arm 225 will dip away from the track 215 as the roller 212 reaches the arcuate segment or surface 230 on the arm, and the timing provided by cam 250 is such that the pickup fingers will drop onto the uppermost sheet of the bundle 50 supported below the pickup cylinder, and the sheet will 55 be withdrawn. Accordingly, this mechanism provides a means for selectively actuating the pickup device at each of the pickup stations, and one or more of the pickup stations can be placed in operation selectively merely by 60 energizing appropriate ones of the latching solenoids 255.

65 The fingers 55 are actually vacuum grippers or pickups, and they are connected to main vacuum manifolds 260 which extend the full length of the assembly apparatus as shown in FIG. 1. A vacuum is produced in these manifolds by a conventional vacuum pump 262 driven from an associated motor 263. Each pickup cylinder 170 has its own vacuum supply conduit 265 communicating with one or the other of the manifolds 260. It will be noted particularly from FIGS. 1, 7 and 10, that the vacuum connection to the pickup cylinder is made through the end opposite its gear drive 175, and as previously explained these drives are alternatively on opposite sides of the machine in order to produce the desired half cycle out-of-phase operation of the successive pickup cylinders.

Each vacuum supply conduit includes a solenoid operated control valve 268, one of which is shown on a larger scale in FIG. 9. Appropriate energizing or deenergizing of the associated solenoid 270 will open or close the valve 268, and therefore the vacuum supply to each one of the pickup cylinders can be individually controlled. In each conduit 265 between the valve 268 and the supply elbow 272 there is a detector mechanism 275. Details of one such mechanism are shown in FIG. 9.

The detector mechanism includes a cylinder member 278 having a cavity 279 which communicates with the main flow passage in the vacuum supply conduit 265 through an opening 280. A piston 282 is mounted in the cylinder, and has a piston rod 283 extending outwardly through the gap 284, terminating in an operating bar 286 for the lever 287 of a switch 290. Spring 292 acts on the rod 283 urging the piston to the right, and so long as valve 268 is open and the operative pickup fingers 55 are not engaged with a sheet, there will be a sufficient inflow of air through the elbow 272 to permit spring 292 to operate the switch 290 into one position.

When the fingers pick up a sheet, the air flow is substantially restricted, and the resulting decrease in pressure in the supply conduit 265 will cause the detector pistons 282 to move to the left, as shown in FIG. 9, against spring 292, and operate switch 290 to its other position. Therefore, when the associated pickup cylinder should carry a sheet off the bundle, and if for some reason there is a miss and no sheet is picked up, this fact will show up by failure of the operation of the associated switch 290.

It will be understood, of course, that the elbow 272 is connected through a suitable rotary seal 294 to the cylinder 185 and support 172, and hence the vacuum supply conduit is connected through passage 178, tube 180, and the flexible hose 199 to the manifold tube 195. The flexible tubing of course permits the relative movement between the manifold and the supply tube 180 which is fixed with respect to the axis of rotation of the pickup cylinder.

The pickup cylinder also is provided, as part of the skeleton cylinder construction, with a segmental sheet support surface 295. This surface is shown in FIGS. 10 and 13, and can be suitably mounted from the tubes 180 and 182; it provides a guide for the sheet trailing behind the pickup fingers 55.

With the foregoing structure in mind, the operation of the pickup cylinder mechanism is as follows. Referring to the position of the fingers 55 as a reference to approximate degrees of rotation of the pickup cylinder, and particularly referring to FIGS. 13 and 14, the cylinder has a circular motion which is accelerating and decelerating, recalling that the line shaft 127 (a or b) has accelerating and decelerating rotational motion derived from the associated drive unit. This motion is therefore transmitted to the pickup cylinder.

The indexing of the cylinder mechanism with respect to the drive shaft 174 (FIG. 10) is such that the fingers 55 will accelerate as they rotate clockwise from the position shown and they will move at a generally rapid rate until the roller 212 approaches the controlling surface 230 on the control arm 225. At this time the drive will be in a decelerating phase and the fingers will be slowing down as the roller 212 passes onto the surface 230. Assuming that the pickup mechanism is set for operation, the arm 225 will drop as shown in FIG. 14 and roller 212 and its arm 210 will likewise drop as shown in FIGS. 14 and 19. Therefore, the fingers 55 will move radially outward of the pickup cylinder under the force of the springs 220, and the open ends of the fingers 55 will strike the top sheet of the bundle 50. Preferably, at this time the fingers are slightly beyond bottom dead center; and they strike the top of the pile just as the fingers begin to rotate up and away from the pile, and as the fingers begin to be moved radially inward by arm 225.

The uppermost sheet of the pile will be picked up by the fingers 55, by reason of the subatmospheric pressure therein, and a fold will be made in this sheet just in advance of the fingers, as shown in FIG. 13. At the same time, the rotary motion of the pickup mechanism is now entirely in an accelerating phase, and thus the sheet will be removed from the pile and then accelerated with the trailing edge folded over flaps of the sheet resting upon and being guided by the support surface 295. By the time the leading edge of the sheet, adjacent the fingers 55, has approached the top dead center position of the pickup mechanism, the sheet will have been accelerated to a velocity matching the velocity of the assembling conveyor; and the sheet will thence be transferred from the pickup fingers to the assembly conveyor at a time when there is little or no difference in speed therebetween.

Recalling that the accelerating and decelerating motions of adjacent pickup cylinders are 180° out of phase, the corresponding cylinders are likewise fixed to their respective drives such that their pickup fingers 55 are 180° out of phase. Thus, when the fingers of the odd numbered pickup cylinders are at top dead center, the fingers of even numbered cylinders are at bottom dead center. This relationship is advantageous, providing for accommodating relatively long sheets on the assembling conveyor while still maintaining compactness in the space between adjacent pickup mechanisms. This arrangement will be more apparent from a consideration of the structure of the assembling conveyor as follows.

Assembling conveyor

The assembling conveyor is provided by a pair of parallel conveyor chains 300. The overall arrangement of these chains is shown in FIG. 1, wherein it will be seen that the lower flight 301 proceeds from left to right, and the upper flight in an opposite direction, being passed around the end sprockets 305 and 306. The chains 300 are at opposite sides of the machine, particularly as shown in FIGS. 7 and 10. The sprockets 305 are fixed to a cross shaft 307, and this shaft receives power from a suitable power takeoff 308 connected to the line shaft 105 and to a countershaft 309 leading into a drive gear box 310 which in turn has its output directed to the shaft 307. Therefore, the power is applied to the assembling conveyor through the sprockets 305, which tend to pull the lower flight 301 along a path extending immediately above the various pickup stations. The sprockets 306 (FIG. 1) are mounted in adjustable carriers 312 so that they can be moved a sufficient amount to provide the proper tension in the conveyor chains.

The chains 300 are of substantial length, as will be appreciated from inspection of FIG. 1. Therefore, the upper and lower flights are both supported throughout substantially their entire length in suitable track members mounted on the framework of the machine. These tracks are best seen in FIG. 7 wherein the lower flights extend between track bars 315 and 316 providing both upper and lower support to the lowermost conveyor flight, which is the active flight of the conveyor. This assures that the active part of the conveyor follows a substantially linear path. The upper flight merely rests upon further track bars 317.

Between the conveyor chains 300 there are mounted a plurality of assembling pin bars 320. Details of these are shown in FIGS. 7, 8, 10, 13 and 21. The bars 320 are bolted to suitable end brackets 322 which in turn are fastened to appropriate links of the chain 300. Along the bar, spaced apart according to the desired ability of the conveyor to handle different widths of sheets, there are a number of barbs or needles 325. These are clamped at their hilt in suitable clamp carriers 327 which in turn have mounting bolts 328 extending through the bar 320 and held in place by suitable nuts as shown in FIG. 8. Thus it is possible to replace the needles readily and to be sure that they are properly sharp and in alignment.

The spacing of the pin bars 320 is equivalent to the spacing between the center lines (or axis of rotation) of two in-phase pickup devices, for example the number 1 and 3 pickup cylinders. It will be recalled that when the fingers 55 for these stations are at top dead center and transferring a sheet to the assembling conveyor, the pickup cylinder in between (e.g. No. 2) will have its fingers at bottom dead center. The sheet or sheets carried on the pin bar receiving a sheet from station No. 3 can trail over the No. 2 station, and almost to the No. 1 station, since the No. 2 pickup is 180° out of phase. Thus as mentioned above, the assembling conveyor is capable of handling sheets which are of considerably greater length than the spacing between adjacent pickup stations, both for this reason and because the sheets are picked up and transferred in a doubled condition as shown in FIG. 13.

Over the pickup stations, and extending from one to approximately the other, there are a plurality of guide plates 330 shown in detail in FIG. 20. These plates have spaces 332 therebetween extending along the direction of conveyor movement whereby the needles or barbs 325 can pass. This relationship will be apparent from FIG. 13, where the needle 325 is shown entering the space, with its lower end extending below the plates 330. The plate in this figure is broken and foreshortened in order to facilitate the illustration.

Likewise, at each pickup station the plates 330 terminate short of the area where fingers 55 can rotate across the plane of movement of the tips of the needles 325. Note for example in FIG. 13 that the upper end of the finger 55 is substantially above the top of the needle 325. Thus each set of plates 330 extends from an area generally overlying the center of a pickup cylinder to an area just short of the adjacent pickup cylinder. This relationship is apparent from FIG. 20. The plates 330 have entrance sections 333 which are somewhat narrower, and which curve downward somewhat such that the ends of the fingers 55 actually move in an arc directly between these portions.

As the folded leading edge of a sheet on a pickup cylinder is carried toward the top of that cylinder, the leading edge will pass over the entrance section 333 of the conveyor guide plates. At the same time, the sheet will be pushed onto the needles 325 of a pin bar, which is traveling over the pickup station in timed relation to rotation of the pickup cylinder. The pins will pierce the folded sheet inward of its leading edge as shown in FIG. 13, and as the gripper fingers 55 release the folded sheet the transfer to the pin bar is assisted by the upwardly sloped sections 333 of the plates 330. Thereafter the sheet is carried by the pin bar, with its trailing flaps sliding over the plates 330.

Therefore, as each active pickup station transfers a sheet from its associated bundle onto a pin bar, these sheets will build up on the pin bars as groups which after the pin bar has traversed the last active pickup station, will comprise all of the sheets necessary to make up a complete pattern. Each pin bar as it moves along the assembling mechanism will thus have assembled on it a complete pattern group.

By appropriate controls for the latching solenoids 255 and the vacuum valve solenoids 270, as will be described, it is possible to program the machine and have only selected ones of the pickup stations actually in operation. Thus with a machine having twenty pickup stations, as actually constructed in accordance with the invention patterns can be assembled having up to twenty different sheets. The range of radial motion of the fingers 55, is sufficient to enable placement of bundles 50 containing as many as 1,000 sheets of the relatively thin paper on which patterns are usually printed. Ordinarily this is a sufficient amount for a "run" of any particular type of pattern, since there will be separate runs for patterns corresponding to the different garment sizes in which the

patterns are available. Likewise, the controls, as will be seen, incorporate sequencing arrangements whereby at the commencement of an assembling and folding operation the pickup stations which are to be used will come into action in sequence, and will be latched out until such time. Such an arrangement is preferred because it prevents the inactive pickup fingers from pounding on the bundle carried on the associated saddle bar, and the fingers do not actually descend until it is necessary for them to pick up a sheet. Specific examples of such sequencing are included hereafter in connection with the description of the sequence controls.

It should also be noted, in summarizing the function of the assembling mechanism, that the different sheets of the pattern may be of different size, and for the best results it is desirable to locate the largest sheet where it will be the last sheet of a group to transfer onto the pin bars. Thus, in the subsequent folding operations the smaller sheets will be enfolded by the largest sheet.

Folding mechanism

The grouped sheets forming a complete pattern are transferred from the pin bars at the end of the assembling conveyor into folding mechanism which may be considered as two related but individual folding devices. The first of these devices to receive the groups of sheets is the stream-folding mechanism which is shown in FIGS. 1, 22, 28 and 29. A typical folding operation of this mechanism is illustrated schematically in FIGS. 26 and 27.

The grouped patterns, having had the sides folded in to form a group of predetermined width such as shown in FIG. 27, are then transferred into the tuck-folding apparatus which is shown in FIGS. 2, 30 and 32. Briefly, the tuck-folding apparatus operates on the grouped patterns to fold them into a predetermined length which can be accommodated in the packaging envelope. These two folding functions will be discussed in their sequence of operation on the pattern groups.

Referring to FIGS. 26 and 27, the group of sheets comprising an assembled pattern is shown as a single line, and the dot-dash center line represents the longitudinal center line of the assembling conveyor and the conveyor of the stream-folding mechanism, as will be described. In a typical arrangement the illustration in FIG. 26 represents successive views of the group of sheets looking from the downstream or discharge end of the stream-folding apparatus. At the top of FIG. 26, in the first illustration marked "A," the group of sheets is shown as it leaves the assembling conveyor, and the small rectangles represent grippers of the stream-folding conveyor which grip the leading edge of each of the groups. The first fold is made on the right hand side, as shown, by folding in a predetermined width of the sheets over the outboard gripper. Next, the second fold is accomplished on the other side of the sheets by folding in a predetermined width of the sheets over the outboard gripper on that side. These outboard grippers are then released and the third fold is made again on the right hand side, now a double under-fold wherein the edge of the first fold is carried over beyond the center line as shown at D in FIG. 26. The final fold is illustrated in FIG. 27 wherein the fourth fold is performed on the left side and carries the edge of the second fold over approximately to coincide with the edge of the third fold.

With the foregoing scheme of operation in mind, and referring to FIG. 1 the stream-folding mechanism is indicated generally at 350, and is made up of several interconnected conveyors. The first conveyor, receiving the groups of sheets from the pin bars, is formed of six conveyor chains, which are shown separately and in section in FIG. 22. These are considered in pairs as constituting different conveyors. Thus, the pair closest to the center line, indicated by the dot-dash line 352 on FIG. 22, is made up of chains 355. These chains are received over sprockets 357 mounted on a supporting shaft 360,

which is shown in FIG. 1 and in FIG. 22. This shaft is located beneath the discharge end of the assembling conveyor. The chains 355 extend the full length of the stream-folding apparatus, and thus pass around a corresponding pair of sprockets 362 which are carried on shaft 363. This shaft is driven from suitable bevel gearing and a line shaft (both not shown) which are on the opposite side of the machine framework from that shown in FIG. 1. The lineshaft is powered through a sprocket and chain drive 364 from the upper lineshaft 165, thus the stream-folding conveyor operates in timed relation to the assembling conveyor.

The second stream-folding conveyor is made up of the pair of chains 365 which are received over sprockets 367, also mounted on shaft 360. The other end of this conveyor is at the sprockets 368, which are mounted on a shaft 369 just past the middle of the stream-folding mechanism.

The third stream-folding conveyor is provided by the chains 375 which are received around sprockets 377 on the shaft 360, and which at their other ends pass around sprockets 378 mounted on shaft 379 located somewhat less than half-way down the length of the stream-folding mechanism.

Thus, the stream-folding conveyor is in effect three different chain-gripper conveyors, of different lengths, which have a common entrance. The conveyor chains 365 and 375 have single spring-loaded gripper-fingers carried therebetween while the chains 355 have a set of triple gripper fingers carried therebetween. Except for the number of fingers in the gripper, the construction is the same, and therefore details of the grippers are explained in connection with the central or three-finger grippers as shown in FIGS. 23 and 24.

Between the chains 355 there are, at regularly spaced intervals, a plurality of gripper mounting blocks, one of which is shown at 380 in FIG. 24. The gripper fingers 382, which may be of a form of spring metal, are fastened at one end to a rotatably mounted shaft 383 on which there is a control gear 384. Meshed with this gear is a driving control gear 385 which in turn is fixed to a rotatably mounted carrier shaft 387. A torsion spring 388 acts between a fixed point on the collar 389 on the shaft 387, tending to urge the fingers to their open position as shown in full lines in FIG. 21 and in dotted lines in FIG. 23. The other end of torsion spring 388 is hooked over a control lever 390 which is fixed to shaft 387. This lever has a roller 392 at its outer end, arranged to cooperate with a control track 395 (as shown in FIGS. 21 and 23) to produce closing movement of the gripper fingers. The fingers in their closed position tend to clamp down on a bar 397 mounted on suitable brackets 398 supported between the chains behind the block 380. Thus, with respect to each of three portions of the stream-folding conveyor, whenever it is desired to keep the corresponding gripper fingers in position, there will be an appropriate length of control track 395.

The transfer area between the assembling conveyor and the stream-folding conveyor is shown in FIG. 21. The pin bar 320 still has a complete group of sheets impaled on its needles 325, but this pin bar is approaching the end sprocket 305. Underneath this sprocket, and over the path of travel of the stream-folding conveyor, there are a plurality of stripper bars or plates 400, having upwardly inclined ends as shown in FIG. 21 extending to above the level of the groups of sheets on the pin bars. Portions of such plates are also shown in FIG. 25. The guide track 402 for the conveyor chains 355 is also shown in FIG. 21, and inwardly from it is the control track 395 for the grippers. It will be understood that in this area the control tracks for all gripper fingers are all the same, and cause the appropriate fingers on each section of the stream-folding conveyor to close at the same time. However, for further reference it should be noted on FIG. 25 that the central or triple gripper fingers 382 have side by

side, on the outer chains 365 and 375, appropriate gripper fingers 382a and 382b.

By comparing the dotted line illustration in FIG. 23 with FIG. 21, it will be noted that in FIG. 21, the gripper fingers have partially closed, and will also be noted from the entrance of the roller 392 onto control track 395. As the grippers come around the sprockets 357 (or the other sprockets on shaft 360) they are fully open and thus their trailing ends can swing in front of the leading edge of a group of sheets on the pin bar as the fingers likewise swing into a position immediately in front of the pin bar. Then, as the gripper fingers begin to close, they swing rearwardly and downwardly with respect to the path of movement, and strip the group of sheets off the needles 325, as will be noted in FIG. 23. With the pattern group thus removed from the assembling conveyor it is now fully controlled by the stream-folding conveyor, and as soon as the group clears the area beneath the end of the assembling conveyor and its sprocket 305, the stream-folding operation begins.

Viewing the conveyor in the same manner as considered with respect to FIG. 26, that is with the pattern group approaching the observer, the first fold is made along the righthand side of the group. This fold is initiated by a stationary folding plow 410 (FIG. 28) which may be of conventional construction formed of a plurality of metallic strips 411 which are arranged in the proper contour to carry the outwardly extending portion of the group, beyond the hold-down plate 412, up and over such plate. The exit end of the stationary plow 410 leads to the entrance of a movable plow 415, of the same general configuration, but having a hinged mounting indicated schematically at 417 on FIG. 29. Thus, this plow can hinge inwardly over the hold-down bar 412, to accelerate the folding operation, and thereby reduce the length of the stream-folding mechanism. The swinging movement of this plow is under the control of a conventional pneumatic cylinder mechanism indicated generally at 418.

After passing the hinged plow 415, the gripper 382b, on the chains 375 is released, and the folded edge of the group passes beneath a creasing wheel 420 (FIG. 25) which produces a sharp crease at the fold line. It will be noted that the hold-down bar 412 terminates just before this creasing wheel. With reference to FIG. 1, the area of release of the grippers 382b can be identified approximately as just upstream of the sprockets 378, and these grippers then pass around such sprockets and back to the sprockets 377 at the entrance of the stream-folder.

This operation is duplicated on the other edge of the pattern group. The gripper 382a carries the edge of the group of sheets, holding it immediately adjacent to the second fold, underneath a hold-down plate 422, after which the outwardly extending portion of the group rises on the stationary plow 425 and the second fold is initiated. The stationary plow is followed by a hinged or movable plow 430, controlled by a pneumatic cylinder 432, which completes the folding operation over the bar 422. Downstream of this folding plow, and immediately before the sprockets 368, gripper 382a releases, the hold-down bar 422 terminates, and the folded edge passes to a creasing wheel 435, as shown in FIG. 25.

After the first two side folds, with the group of sheets folded as shown at C in FIG. 26, the outboard grippers 382a and 382b having been released, the pattern is prepared for the next folding operation in the stream folder. Thus, as shown in FIG. 1 and in FIG. 25, the group is next drawn onto a stationary folding plow 440, and a hold-down bar 442 is provided along the inner edge of the plow to form a surface about which the fold is made. This bar can be supported, for example, from the overhead support bracket 443 as shown. At the exit from this folding plow there is a further creasing wheel 445 cooperating with an elongated plate or track 446, whereby the fold is creased. This fold represents one side of the ultimate width dimension of the pattern group, this width

being indicated at E in FIG. 25, and of course corresponding to the width shown in FIG. 27.

On the other side of the pattern group the second enfolded edge rides along the plate 448, and after the fold is completed by the plow 440, the final stream-fold operation is performed by drawing the group of sheets past the stationary plow 450. This plow also cooperates with a hold-down bar 452 which may be suspended from the bracket 453, and a creasing wheel 455, mounted over a plate 456 at the exit of plow 450, performs the final crease fold in the same manner as previously.

Tuck folding mechanism

The four stream-folding operations are thus complete, and the group is carried by the main stream folding conveyor grippers 382 into a tuck-folding mechanism which is shown in FIGS. 2, 30 and 32. The center stream-folding conveyor ends at the sprockets 362 (FIG. 1), and there is a power takeoff from the shaft 363 on which this sprocket is mounted, including a drive sprocket 460 (FIGS. 30 and 32) which receives a drive chain 462. This chain leads over a driven sprocket 463, as shown in FIG. 32, and the driven sprocket in turn is fixed to a first folder drive shaft 465. An idler sprocket 467 also engages chain 462, and is carried on an adjustable arm (not identified) in conventional fashion to provide proper tension in the drive chain 462.

The power for the belt conveyors and other moving parts of the tuck-folding mechanism is derived from shaft 465, and particularly from a drive gear 470 fastened thereto.

By comparing FIGS. 30 and 32, the drive to the various belt conveyors in the tuck-folding mechanism can readily be seen since the shafts which are shown in section (cross-hatched) in FIG. 32 correspond to shafts on which the various belt conveyor pulleys are shown mounted in FIG. 30. The first of these is the shaft 472 on which is fastened a small drive gear 473 meshing with the main gear 470, and providing the drive for a pulley 475. This pulley in turn drives the conveyor belt 477 which extends partly over the end of the stream-folding conveyor, as shown particularly in the lower right corner of FIG. 1. The other end of this belt passes over a guide pulley 478, and an adjustable pulley 479 is likewise provided over the upper flight of belt 477, being mounted in a conventional way or a movable arm to maintain tension in the belt.

This belt conveyor is arranged to press on the top of the folded group of pattern sheets, and cooperating with the plates 446 and 456, carries this group into the entrance of the tuck-folding mechanism as defined by the deflector plate 480. Downstream from this point the relatively long and narrow pattern passes between the belt 477 and a further conveyor belt 485. This second belt has its upper flight, which engages the undersurface of the pattern group, extending over a support plate 486. The conveyor belt 485 passes around its drive pulley 488 and a smaller idler pulley 489 which is mounted beneath the lower flight over conveyor belt 477. A tension adjusting pulley 490 engages the outside of the lower flight of belt 485.

Pulley 488 is mounted on a shaft 492 to which is also fastened a driving gear 493. This gear, as shown in FIG. 32, is rotated through an intermediate gear 495 which is meshed with both gears 493 and 470. Immediately above the pulley 488 there is a movable drive nip roll 497 which is mounted to rotate freely on the end of a swinging or pivoting arm 498. A portion of this arm also is shown in FIG. 32, and it is carried on a shaft 499.

The central or transfer gear 495 also drives a main control gear 500, and this gear carries a number of control cams, which are shown only schematically in FIG. 32 by the segment lines 501, 502, 503 and 504. It will be understood that these cams are individual rotatable cams of conventional construction which are adapted to pro-

vide a timed rise and fall of their corresponding followers.

The first follower is a roller 505 which rides on the cam 501, and which in turn is carried on one end of a swinging arm 508. This arm is pivotally mounted on a stub shaft 509. The other end of the arm is attached through a connecting rod 510 to the crank arm 512 which is fastened to shaft 499. A spring 513, anchored at any suitable point on the machine frame, acts on the linkage as shown schematically in FIG. 32 tending to hold the follower 505 against cam 501. The construction is such that at an appropriate time during passage of a group of sheets through the tuck-folding mechanism, the follower 505 will drop and the spring 513 will pull the linkage causing shaft 499 to rock in a clockwise direction as viewed, swinging the roll 497 downward as viewed in FIG. 30 against the group of sheet passing therebeneath.

Thus, the roll 497 assures proper contact between the pattern group and the belt 485 for continued feeding action. The forward edge of the pattern group passes over the guides 520 which form between them a tuck-fold opening, indicated by the general reference numeral 522. Beyond this opening there is a support plate 524, and at the end of this plate a stop 525 including an upwardly angled deflector. The pattern group is projected by the feeding action of belt 485 so that its leading edge eventually engages the stop 525. At this time a tuck-folding blade 530 is caused to descend at approximately two-thirds of the pattern length from the leading edge, and force the pattern down into the opening 522. The blade 530 is mounted on the end of the arm 532 and this arm is fastened to a rocker shaft 533 which is suitably mounted to rotate about its axis. As shown in FIG. 32 this shaft is fastened to an arm 534, and at one end this arm is attached through a connecting rod 535 to a further rocker arm 537 which is pivotally mounted in the frame, and which carries a roller follower 538 held in contact with the cam 502 by reason of the force of spring 539 acting through this linkage from its connection with the arm 534.

The doubled portion of the pattern then is pushed into the opening 522, which in turn leads to a nip formed between the belt 485 and a further conveyor belt 540. This belt passes around a pulley 542 which is mounted on a swinging arm 544, and around a smaller stationary pulley 545. The arm 544 pivots about a short shaft 547, and it is maintained in a desired position by a rod 550 connecting at one end to the arm 544 and passing at its other end through a stationary bracket or stop 552. A spring 553 acts between the bracket and a collar on rod 550 tending to move the rod counterclockwise as seen in FIG. 30, and the limit of this movement can be determined by adjusting a knob 554 threaded to the end of rod 550. Pulley 542 can thus yield to accommodate a variable thickness through the nip.

The belt 540 travels past a stationary guide plate 555, so that the pattern passes therebetween. Immediately below the lower end of this plate there is a further swingable roll or wheel 560 mounted on a swinging arm 562. This arm is carried on, and fastened to, a rocking shaft 563.

Referring to FIG. 32, the drive for the conveyor belt 540, and the control for swinging the roll 560 are both shown. The drive includes the pair of gears 565 and 566, the first meshing with gear 493 and the second meshing with a driven gear 567 which is fastened to a shaft 568 carried in the arm 544, and also fastened to the hub of the pulley 542. The arrangement is of a known type, whereby the arm 544 can swing to move the center of gear 567, but gears 566 and 567 remain in mesh.

The shaft 563 is fastened to a control arm 570, and this arm carries at its end a roller follower 572 which follows the cam 503, with a suitable spring 573 attached between the other end of arm 570 and the frame, provid-

ing the force which maintains contact between the follower and the cam. At the appropriate time, the roll 560 swings toward conveyor belt 540 and functions to assure that the folded pattern is fed downwardly toward the next tuck-folding station.

This station is formed by an adjustable mounted guide plate 575 across which the once-folded pattern passes toward the adjustable stop mechanism, shown generally at 577. In passing toward this stop the pattern travels across the second tuck-fold opening 580, formed by the guide bars 582. Once the leading edge of the folded pattern engages the stop 577, a second blade 585 swings into the pattern to make the final tuck-fold and force the pattern into the last folding nip. The general sequence of this operation is apparent from FIGS. 3 and 30.

This last folding nip is formed by a pair of cooperating conveyor belts 588 and 590. The upper belt 588 passes over a roller 592 which is fastened to a shaft 593. Rotary power to this shaft is provided by a gear 594 carried on the shaft and meshing with the central gear 500. There is also a smaller transfer gear 596 on this shaft and it in turn drives a further gear 598, and this gear drives a pair of counter-rotating gears 600 and 601. The shaft 602, on which gear 600 is mounted, also forms the pivot mounting for an arm 605, and this arm mounts the roller 608 within the end of the lower conveyor belt 590. A shaft 610 connects gear 601 and roller 608 to provide the lower conveyor belt drive.

Thus, the last tuck-folding nip is defined by the rollers 592 and 608 and the belts 588 and 590 passing thereover. Blade 585 is mounted on a swinging arm 615, and the motion of this arm is controlled by a rocker shaft 617 pivotally mounted in the frame and fastened to the rocker arm 618. One end of this arm is fastened through a connecting rod 620 to a further rocker arm 622 mounted to pivot about a stub shaft 623. Arm 622 carries a cam follower 625 which is held in contact with cam 504 by spring 626, acting on rocker arm 618 and through the aforementioned linkage.

In the tuck-folding mechanism, therefore, the patterns received from the stream-folding mechanism are moved against the stop 525, and the blade 530 descends against the pattern at a point approximately two-thirds of its length from the leading edge, creating the first tuck-fold as shown in FIG. 3 by forcing this part of the pattern into the first tuck-folding nip. This part then becomes the leading edge of the pattern, and it is guided against the second stop 577, which can be adjusted according to the length of the pattern being folded, and the second blade 585 swings against the pattern at the appropriate time and forces a portion of it into the second tuck-folding nip 580, at which time this last portion of the pattern becomes the leading edge and the pattern enters the exit conveyor formed by the belts 588 and 590, having been folded twice upon its own length.

Reject mechanism

The remainder of the conveyor structure, although driven from the tuck-folding mechanism and in timed relation thereto, serves also as a means to carry the folded patterns into and through the reject mechanism. This mechanism is shown in FIG. 30, and functions as follows.

The upper conveyor belt 588 passes around stationary guide rollers 630 and 632, the latter being mounted on a movable arm 633 for tension adjustment. In addition, intermediate the rollers 592 and 630, there is a guiding roller carriage 635 providing a mounting for a pair of backup rollers 636. This carriage is supported on a swinging arm 637, and it is provided with a predetermined pickup force by means of a spring 640 acting through an internal rod 642, which in turn is connected to the carriage through a link 643. The stress of the spring can be adjusted by the knob 644 threaded to the end of the rod 642.

The rollers 636 cooperate with a pair of driven rollers

650 and 652 which are on the opposite side of the belt 590. Thus, the upper carriage and its rollers tend to press the two conveyor belts together and against the driving rollers. The remainder of belt 590 passes around a free-rotating guide pulley 653, a further guide pulley 654 and a lower guide pulley 655 which is mounted on a swinging arm 656 to provide for tension adjustment if desired.

The power to rollers 650 and 652 comes from their shafts 660 and 662 and these in turn are fastened to gears 663 and 664 meshed with a drive gear 665. This gear in turn is driven from a transfer gear 667 which is driven through sprockets 668 and their connecting chain 670, the sprocket drive running from the gear 598. The idler sprocket 672 is mounted on an arm as shown in FIG. 32 merely to maintain proper tension in the chain.

As the folded patterns pass the area of roller 630, they leave the upper conveyor belt 588 but the lower belt 590 continues for a short length and moves under a further conveyor belt 675. The first portion of the path of this belt is shown in FIG. 30, and the second or downstream portion is shown in FIG. 33.

The drive for this conveyor belt is discussed further on, and in connection with the downstream supporting parts 25 of the belt. The portion shown in FIG. 30 is passed around a guide pulley 677 which is mounted to rotate in a fixed position on the frame, and about an upper guide pulley 678 mounted on a swingable arm 679. The belt 675 passes over the reject station, and the reject mechanism is shown generally at 680.

Details of this mechanism are shown in FIG. 31. It includes a movable shoe 682 mounted to pivot on a supporting shaft 684. The upper face of this shoe forms a guiding plate beneath the conveyor belt 675, and when an acceptable folded pattern reaches this station it will pass over the shoe, being moved along by the belt 675, and with the upwardly extending flanges 686 forming side guides on the shoe to assure that the pattern remains centered even though it is now contacted by only one moving belt. The normal position of the shoe is shown in solid lines in FIG. 31.

If for some reason a pattern is incomplete, and the device for producing a signal to this effect will be explained later on, then the shoe 682 can be lifted by energizing the reject solenoid 690. The armature of this solenoid is connected to link 692 to the shoe, and when the solenoid is energized it will lift the shoe as shown in dotted lines in FIG. 31. This will move the deflector plate portion 695 of the shoe upward to intersect the path 45 of movement of the pattern coming through between the belts 675 and 590, and the pattern will be directed downward and out of the conveyor mechanism, as indicated generally by the arrow 696. A suitable receptacle can be provided below the reject mechanism if desired, but this receptacle is not shown in the drawings.

Guide sheet inserter

The conveyor belt 675 also carries the acceptable patterns past the reject mechanism and into a guide sheet inserter mechanism. The function of this mechanism is to add to each folded pattern a guide or instruction sheet 70 72, and in the form of mechanism disclosed herein a single guide sheet is removed from a pile thereof, entered 65 into the conveyor system, and the folded pattern is dropped on top of the guide sheet in timed relation to its movement. The general form of this operation is shown 75 in FIG. 3, wherein the folded patterns are shown moving downward at a slight angle and the guide sheet 72 is shown as it moves in the direction of the arrow thereon, first laterally underneath the path of movement of the patterns, and then along the path of pattern movement with a pattern being placed on top of each guide sheet. The inserter mechanism which performs this function is shown in FIGS. 33, 35 and 36.

Referring to FIG. 33 the conveyor belt 675 passes around further guiding pulleys or rollers 698, which are mounted in stationary position from the frame, and rollers 699 which are mounted on suitable swinging arms for tensioning purposes, as shown. To one side of the conveyor belt 675 there is a hopper or magazine 700, formed by spaced vertically extending plates 701, and this hopper is adapted to contain a supply of the guide sheets 72 as shown in FIG. 35. At the bottom of the hopper there are supporting brackets or angles 702 which extend inwardly a short distance to support the bottom of the pile of sheets at its edges.

A vacuum feeder is provided to pick the sheets one at a time from the bottom of this pile, and this feeder is in the form of a curved tube (or tubes) 705 having a suction head gripper 707 at its end adapted to swing against the lowest sheet in the pile. The tube 705 is fastened in a rotatable bracket or arm 708 carried on a shaft 710, and rotation of this shaft is in turn controlled by lever arm 712, the connecting rod 713 extending from that lever arm, and the control or cam follower arm 715. This arm has a pivot mounting at its other end on the stub shaft 716, and it is provided with a cam follower 718 arranged to follow a control cam 720 mounted on the timing shaft 722.

The vacuum supply to the tube 705 is not shown, but can be taken from the same main vacuum manifold previously described, and may include suitable valve arrangements of known design to control the vacuum supply to the tube in accordance with its swinging movement. Basically, this arm swings between the positions shown in full and in dotted lines in FIG. 35, the full line position being the normal or "ready" position and the dotted line position representing the limit of movement of the feeder to carry a single guide sheet down and pull it away from the supporting brackets 702.

When this feeding movement occurs, in timed relation to the conveyor drives, as will be explained, one edge of the guide sheet is placed on a transversely extending conveyor belt 725. This belt is passed over a pair of rollers 726 and 727, the latter being the driving roller, and the belt extends under the path of movement of the conveyor belt 675. A stop plate 730 extends over the uppersurface of belt 725 and functions to limit the movement of a guide sheet thereon.

When the edge of a guide sheet is placed on belt 725, a nip roller 732 is swung downward onto the top of this leading edge of the guide sheet, to assure that this sheet is picked up and carried across by the belt to the stop 730. This nip roller is mounted on a swinging arm 735 pivotally mounted by a rod 736. The rocking or swinging movement of the arm is produced by a connecting rod 737 which extends to a follower arm 738, and this arm has a roller follower 739 engaging a further control cam 740 on the timing shaft 722. The design of cams 720 and 740 is such that the lowering of a guide sheet and the engagement thereof by the nip roller occurs in that sequence.

Power to rotate the nip roller is transferred from the timing shaft 722 by suitable timing belt drives which are indicated by the general reference numerals 742 and 743, and shown in dot-dash lines. Any suitable drive arrangement can be provided for this purpose.

The drive for the timing shaft and for the conveyor belt 725 is derived from the driving mechanism shown in FIG. 32, and an extension of which is shown in FIG. 34. Thus, a chain and sprocket drive 745 extends from the shaft of the driven sprocket 668, over an idler 746 which is also shown in FIG. 34, to a countershaft 748. This countershaft in addition to the driven sprocket of the drive 745, also carries the driving sprocket of a chain and sprocket drive 750, the driving gear of a timing belt drive 752, and a control cam 755. The output of the timing belt drive 752 is transferred to a

gear 756, and this in turn drives through bevel gearing 757, the driving roller 727 and the conveyor 725. On the shaft of this roller there is a pinion 758 which meshes with a larger driven gear 759 carried on the timing shaft 722. The arrangement is such that the timing shaft rotates at the same speed as the conveyor drives, while the drive to the conveyor 725 is at approximately twice this speed.

It will be noted from FIG. 33, that the conveyor belt 725 is of substantially less width than the guide sheets. This relationship is apparent by comparing the belt with the spacing of the hopper plates 701. Accordingly, the side edges of the guide sheet extend beyond the belt 725, and one edge of the guide sheet, which eventually becomes the leading edge in the operation, is carried over the entry of a conveyor provided by the belt 760. This belt passes over an idler roller 761, a further small idler 762, and around a path of driving rollers 763 on shafts 764. These rollers rotate in the same direction as shown, and are mounted toward the exit end of the conveyor belt 760, immediately beneath the idler rollers 699 of the conveyor belt 675.

At the entrance to belt 760, immediately above the roller 761, there is a further nip roller 765 carried on a swinging arm 766 which is fastened to a control shaft 768. The motion of this shaft is in turn controlled by arm 770 (FIG. 34) which has a roller follower 772 following the cam 755 and held in contact with the cam by the spring 773. The timing is such that when a guide sheet reaches the stop 730, the nip roller 765 descends and pushes the edge of the sheet against the moving belt 760, at which time the sheet is picked up and carried on this belt toward the region where it meets the upper belts 675, at the guide roller 699.

35 The folded patterns are carried from the reject mechanism (and over the conveyor belt 725) by a relatively small guide belt 775 which passes over the rollers 776 and 777, the latter being mounted on a swinging arm 778 to maintain proper tension in this belt. It does not have a direct mechanical drive, since it serves merely as a guiding device to hold the folded patterns in contact with the driven belt 675.

Immediately downstream of the end of belt 775, at the roller 776, the folded patterns are free to drop onto 45 the belt 760, in the region designated by the reference numeral 780, and when a pattern reaches this position a guide sheet 72 will likewise be in position on the belt 760 such that the pattern drops on it. The relationship of folded pattern and sheet is not shown in FIG. 33, but 50 is shown schematically in FIG. 3.

Packaging apparatus

It will be clear from FIG. 33 that the combined folded patterns and guide sheets are carried, still in a timed 55 relation, between the conveyor belts 675 and 760, and these belts separate at the packaging supply outlet 782. This outlet is adjacent the bottom of an envelope magazine or hopper 785. This hopper is formed of a plurality of vertically mounted plates 787, and at the bottom of 60 these plates there are inwardly extending supporting brackets 790, which hold the edges of the last or lowermost envelope in the magazine.

Details of the packaging mechanism are shown in FIGS. 37 and 38, and in FIG. 37 the lowest envelope 75 75 is shown with its flap 75a open, and the body of the envelope depending, whereby the mouth 75b is open. A stream of air under slight pressure preferably is directed 65 toward the lowest envelope from one or more pipes 792 to assist in holding this envelope in an open position 70 to ready to receive a pattern and guide sheet. Beneath the end rollers 764 of the lower conveyor there is a guide arm 795 mounted for pivoting movement about a support 796 on the frame, and having a conventional adjustable spring loading or positioning mechanism 797, of the same type previously described, tending to move the

arm 795 counterclockwise. At the top of this arm there is a roller 798, and this roller preferably has one or more grooves in its surface in the region where the air pipes 792 pass, in order to provide room for these pipes.

The roller functions to press the combined pattern and guide sheet against the undersurface of the support bracket 790 thereby assuring that the pattern is aligned with the mouth 75b of the envelope. The thrust exerted on the pattern and guide sheet coming from the conveyor belts is sufficient to carry them into an envelope. Immediately thereafter, the packaging mechanism operates to remove the stuffed envelope from the magazine.

This mechanism, referring to FIG. 37, includes a diamond-shaped rocker arm or plate 800 mounted on a pivot support 801 and carrying one or more suction tubes 802 terminating in suction pickup cups or heads 805. The tubes are maintained in alignment and mounted from the plate 800 by means of a cross-rod 806 projecting from the plate. The timed rocking motion of the arm or plate 800 is produced by a lever arm 808 fastened to a rocker shaft 810, and connected to plate 800 by the link 811. This shaft is seen also in FIG. 34 together with its adjustment to a drive arm 812 having a cam follower 813 at its end.

The gear train from which the driving power is obtained is shown in FIG. 34. The input gear to this train is a gear 815 which is rotated from the sprocket drive 750. Since the various gears and their directions of rotation are shown in the drawing, only those gears or shafts which have a specific output function will be identified specifically, and the gear train as a whole is designated by the general reference numeral 818. One of the gears of this train, identified as a control gear 820, is connected to drive a cam 822, a portion of this cam being shown in contact with the follower 813. Thus the rocker shaft 810 is caused to move and produce appropriate motion of the vacuum tubes 802. The other end of the arm 812 is provided with a control spring 823 which functions to hold the follower in contact with cam 822. Further gears in the train are connected to rotate the shafts 764 of the lower belt conveyor 760.

As the bottom edge of an envelope 75 is withdrawn from the magazine or hopper, as shown in FIG. 38, it is placed in the path of movement of a scissor-like pickup member. This member includes an arm 830 fastened to a rocker shaft 831. At the upper end of the arm 830 there is a fixed gripper bar 832, and cooperating with it is a movable gripper bar 834 mounted on a swinging arm 835. This arm is carried by a short shaft 836 pivotally mounted to the arm 830, and control of the small arm 835 is obtained through swinging a lever 837 fastened to the shaft 836 and moved under the control of a conventional pneumatic cylinder 838.

Motion of the entire arm assembly, by swinging the arm 830, is produced from a control arm 840, shown in FIG. 34, which is fastened to shaft 831, and which has a follower 842 urged into contact with a control cam 843 by spring 844. The cam 843 is also driven by the control gear 820.

Operation of this pickup mechanism is generally as follows. When the vacuum heads 805 draw the bottom edge of an envelope out of the hopper and a pattern and guide sheet has been loaded into the envelope, the arm 830 swings from the normal position, shown in FIG. 37, upward toward the end of the envelope, so that the bars 832 and 834 are on opposite sides of the deflected end. Then, the pneumatic cylinder 838 is actuated to bring the movable bar 834 downward and the envelope is gripped between the bars as the arm 830 returns toward its normal position carrying the envelope away from the hopper.

During this motion, the envelope is drawn into a discharge nip 845 formed between the rollers 847 and 848. Roller 847 is mounted in a stationary position on the frame, fixed to a driven shaft 849. Roller 848 is mounted

70

for free rotation on the end of a swinging arm 850. The position of this arm is determined by an adjustable spring biasing mechanism 851, of the same type as previously described.

When the bottom edge of the envelope is drawn between these rollers, it is literally propelled through the rollers and onto a discharge conveyor belt 855. Referring again to the gear train, shaft 849 is driven therefrom as shown in FIG. 34, and the discharge conveyor drive gear 856 is likewise driven from this train through shaft 857 and gears 858. The packaged patterns require only closing of the flaps of their envelopes, and thereby discharge from the apparatus on the conveyor belt 855.

Control system

FIGS. 39 and 40 show the mechanical parts of the control system for the machine, whereby it is stopped and started, and whereby patterns having less than the required number of sheets therein are removed from the machine by the reject mechanism during operation of the machine. The schematic diagram showing the electrical control circuits includes FIGS. 41A, 41B, 41C, 41D and 41E, and FIG. 42 is a diagrammatic representation of the control cams which operate certain switches in the circuitry, and which are driven in fixed relation to the machine and particularly to the memory mechanism.

Referring to FIGS. 39 and 40, the memory mechanism includes a wheel or disc 875 which is adjustably mounted on a hub 876 and driven from a gear box 877. The power to this gear box is obtained from a timing belt drive 879 which in turn derives its power from the constantly rotating line shaft 125b, which is driven from the head end of the machine as previously explained. Similarly, the control cams shown in FIG. 42 are mounted on a common shaft, represented by the dotted line 880, and this shaft is driven from a timing belt drive 882, the shafts and cams being mounted in a housing 883 as shown in FIG. 39. The memory wheels and the cams thus rotate in fixed relation to the drive of the entire machine.

A segment of a peripheral part of the memory wheel 875 is shown in FIG. 40A, and includes a sleeve 885 providing a mounting for a memory pin 890. There are a number of these pins spaced about the memory wheel as shown in FIG. 40A, and each pin is adapted to move between one of two positions, being held in either position by a detent which is shown generally at 892. Whether or not a given one or more of these pins is displaced determines the "memory function" of the control as will be explained.

55
60
65
70

The pins 890 are normally in the position shown in FIG. 40A, which will hereafter be termed the "clear" position. The pins can be transferred to the opposite or "reject" position if they are struck by the armature head 893 of a solenoid 895. There are a number of such solenoids arranged in a crescent along the bottom of the memory wheel 875, being mounted in the bracket 897. The coils of these solenoids are designated in FIG. 41D as L-41 through L-60, there being one such reject solenoid for each pickup station, or twenty in number. As will be explained later in detail, these solenoids are energized in response to lack of a sheet being fed to the assembling conveyor at the corresponding pickup station.

If anyone of these reject solenoids is energized, the memory pin opposite it will be displaced; and when the displaced pin or pins reaches the top of the memory wheel it will operate to close the reject switch S-58. The position of this switch is shown in FIG. 40, and its place in the control circuit is shown in FIG. 41E. The time required for the displaced pin to move from the solenoid which actuated it around to the position of switch S-58 will correspond to the time for the pattern in the machine to travel from the pickup station, at which the reject signal was derived, to the reject mechanism, where that pattern will be segregated and removed from the machine as described. After passing the switch S-58, the pins pass a

station in the area indicated generally at 898 where the pins are all reset to the normal or "clear" position. This function can be obtained by mounting a suitable ramp (not shown) adjacent to the memory wheel.

Before describing the control system and the circuitry in detail, it is desirable to reference certain of the parts to the mechanism previously described. For example, the solenoids L-41 to L-60 have been identified as the bank of reject solenoids, one of which is shown at 895, and the physical mounting arrangement of which is shown in FIGS. 39 and 40. The circuits which control energizing of these solenoids incorporate corresponding normally open switches S-35 to S-54, shown in FIG. 41D. Each of these switches corresponds to a detector switch 290 such as shown in FIG. 9, and previously described as being closed in response to a drop in vacuum at a pickup station when that station has missed feeding a sheet.

Similarly, the solenoids L-1 to L-20, shown in FIG. 41C represent the solenoids 270 of the vacuum control valves 268, one of which is shown in FIG. 9. The designations of the solenoid coils correspond to the pickup station at which they are located. Similarly, the solenoid coils L-21 through L-40 shown in FIG. 41C represent the coils of the solenoids at each station corresponding to the latch control solenoid 255 shown in FIG. 16. It will be recalled that energization of these solenoids, or lack thereof, determines whether or not the corresponding pickup station should be in operation.

Referring to FIG. 41A, the electrical power to the entire machine is represented by the power supply lines 900, shown as a three-phase sixty-cycle A.C. supply. All three lines of this supply are connected to the main drive motor 90 through the contacts K-1a of the relay K-1. Its coil is so designated in FIG. 41A. Likewise, two of the power supply lines are connected to the primary winding of a stepdown transformer 901, and its secondary coil constitutes the supply of control voltage for the machine. In FIG. 41A this control voltage is thus applied across the lines 902 and 903 which may be suitably fused as shown. In the circuit line of relay coil K-1 there is a normally closed motor-stop switch S-2 and a normally open motor-on switch S-3. If the motor-on switch is closed, this energizes relay K-1 to supply power to motor 90, and also completes a holding circuit around switch S-3 through the contacts K-1b.

Next, closing of the normally open start switch S-9 will complete a starting circuit through relay coil K-6, around its locking contacts K-6a, and through a safety circuit. This safety circuit includes normally open series connected switches S-61, S-63, S-65, S-67, S-69, S-71, S-73, S-75, S-77 and S-79, across which there is a parallel circuit through a cam operated switch CS-11. In series with that portion of the safety circuit is the series connected sequence of switches S-62, S-64, S-66, S-68, S-70, S-72, S-74, S-76, S-78 and S-80, and connected in parallel with them is the cam operated switch CS-12. These switches (S-61 through S-80) are located one at each station, corresponding to their odd or even number, and they are operated off the control shaft 227 (FIGS. 14 and 16) whereby they are closed during a pre-determined portion of one revolution of the machine drive.

Recalling the description of operation of the pickup stations, these odd and even numbered switches will be closed and opened at opposite times, and thus the cam switches CS-11 and CS-12 are arranged to close 180° out of phase with each other and with the switches across which they are connected. It is necessary for a complete circuit to exist through this safety circuit, and through the additional safety switches S-92, S-93 and S-94, in order to supply power to relay K-6 when the start switch is closed by the operator. Assuming that the safety circuit is complete, K-6 will be energized and lock in through its contacts K-6a. This in turn closes the contacts K-6b in the circuit of relay K-2 and the con-

tacts K-6c in the circuit of relay K-5. The machine is then prepared either to jog or to run, at the command of the operator.

To jog, the operator closes the jog switch S-13 and this completes a circuit through the normally closed stop switch S-12 and through the normally closed contacts K-4a and the now closed contacts K-6b to energize the relay K-2. Then K-2 energizes the contacts K-2a in the circuit of relay K-5 and it in turn is energized to open its normally closed contacts K-5a in the brake circuit and to close its normally closed contacts K-5b in the clutch circuit. This releases the main brake 96 and engages the main clutch 98, and as long as the operator holds switch S-13 depressed, the machine will turn over. However, if he releases this switch, the circuit to relay K-2 immediately is broken and the machine will stop. The jog circuit is used for adjusting and setting up the machine for continuous operation.

If the operator closes the run switch S-14, this completes a circuit through stop switch S-12, and the normally closed contacts K-4b to the coil of relay K-3. With this relay energized, it completes a holding circuit through a holding contact K-3a and the normally closed contact K-4c, and also closes K-3b in the circuit of the delay relay KTD. At the same time, a warning circuit is completed through the normally closed contacts KTDa and the warning horn HN-1. Relay KTD is of the delay type and it will not transfer its contacts for some time after it is energized, for example several seconds. During this interval the horn is sounded as a warning that the machine is about to begin a full automatic run. Once the delay relay transfers its contacts KTDa contacts open and the horn is shut off, and KTDb contacts close, completing a bypass circuit from the stop switch S-12 to contacts K-6b, holding in relay K-2. At that time the run switch S-14 can be released and it will open without any effect on the running circuit of the machine. The machine is now in its automatic regime, and it will be assumed that a run of pattern folding operations has commenced.

The sequencing controls which govern the starting up and shutting down of the automatic operation are shown in FIG. 41B. Power is supplied to this control circuitry through a separate stepdown transformer 911 (FIG. 41A), and its secondary winding is connected to the circuit supply line 912 and 913. In this circuit there are two twenty-two-position stepping switches, designated SS-33 and SS-34. The first position of each stepping switch is labeled H, for the home or beginning position, and it will be noted that in each case there is no circuit connection at the H contact.

In each of the contact positions labeled 1 through 20 of these two stepping switches there are circuit lines including the contacts of double-pole single-throw (DPST) manually operated switches, designated S-15 through S-34. These switches are mounted on an operating panel (not shown), and they are set to their open or closed positions by the operator according to which pickup stations are to operate during a given run. For example, to operate the first station the operator closes switch S-15 and this closes the switch contact at the number 1 contact at each of the stepping switches, setting up a possible circuit through the stepping switch wiper. In each circuit of the contacts of SS-33 there are relay coils designated K-11-L through K-31-L. These are representative of the latching relays which can remain in a given position without need of a holding circuit. Similarly, the contacts of stepping switch SS-34 have individual circuits incorporating the relay coils K-11-R through K-31-R, and these represent the relays or unlatching coils of the same latching relays. Twenty of these latching relays, which can be identified as relays K-11 through K-30, are arranged in the corresponding twenty circuit positions or contacts of the stepping switches, and they correspond to the twenty pickup stations of the machine.

Relay K-31 is a control latching relay for governing the coordinate operation of the two stepping switches.

The master switch for this portion of the control circuit is the manually operated switch S-55. The operator closes this switch whenever he closes any of the other control switches S-15 through S-34. When the machine then begins a run, the cam switch CS-1 will close momentarily to complete a circuit through the normally closed contacts K-31a and K-32a to the relay coil SS-33. This is the coil of the stepping switch SS-33, and this momentary completion of the circuit causes the stepping switch to advance from its home position to its number 1 contact. In turn, that completes a circuit through the normally closed contact K-31b, the wiper of SS-33, and the relay coils K-38-L and K-34. The latching relay K-38 then remains in its energized position and closes its contacts K-38a which are connected across the cam switches CS-1 and CS-2. The coil K-34 is the reset coil for the stepping switch SS-34, and when energized returns that stepping switch to its home position.

For purposes of explanation it will be assumed that pickup station number one will be used, and switch S-15 is closed. Thus, a circuit is also completed through S-15 and to latching coil K-11-L of the latching relay corresponding to the first station. This causes contacts K-11a in the circuit of solenoid valve L-1 to close (FIG. 41C), opens the contacts K-11b in the circuit of the latching solenoid L-21, and closes the contacts K-11c which are in the circuit of the first reject solenoid coil L-41 (FIG. 41D). As a result, the latching solenoid of the first pickup station is deenergized and the pickup mechanism is free to operate during each revolution that it makes; the vacuum valve at that station can be energized and the vacuum supply is ready to be completed to the pickup tubes at the first station, and the rejection circuit for the first station is prepared for operation in the event that there is no pickup.

Referring to FIGS. 41C and 42, when cam III closes switch CS-3 all the pickup mechanisms at the odd numbered stations (i.e., 1, 3, 5, etc.) will be descending toward the bundle of sheets on the associated saddle bar. In other words, with reference to FIG. 13, the tubes 55 will extend approximately straight downward. At the time cam III closes switch CS-3, a circuit is completed through the closed contacts K-11a and through the coil L-1 of the solenoid valve at the first station, and the vacuum supply is completed for a pickup of a sheet at that station. In the event that there is no pickup, the associated detector will operate, and switch S-35 (FIG. 41D) will close preparing a circuit through the closed contacts K-11c and the reject solenoid coil L-41.

The foregoing description of operation applies to all of the pickup stations, and to their associated latching solenoids, solenoid operated vacuum valves and reject solenoids. The only difference in function during the starting up and running operation will be as between the odd and even numbered stations. In that respect, cam switch CS-4 is closed by cam IV at approximately 180° out of phase with switch CS-3. The reason for this is, as will be recalled, that the odd and even numbered pickup stations function 180° out of phase. Similarly, the reject control cam switches CS-7 and CS-8, which are in parallel for the same reason as CS-5 and CS-6, will also operate 180° out of phase to control power supply to the reject solenoid circuits of the even numbered stations.

So far only the possibilities of operation at the first station, at the number one contact of SS-33, have been considered whereupon K-11-L was or was not energized according to whether switch S-15 had been closed to place the first pickup station in operation. The operation of this station will occur within one-half of a complete rotation of the cam shaft 880. At this time K-38-L has been energized, relay K-38a remains closed until the latching coil relay K-38 is released. About

180° after CS-1 was closed, cam II will close switch CS-2 to provide a further power pulse to the coil SS-33 of the first stepping switch, and it will advance to its second contact, where a similar possible circuit sequence can occur through S-16 and K-12-L. If the second position is in operation S-16 will have been closed, and the same events will occur with respect to the circuits embodying the contacts K-12a (from CS-4) K-12b, and K-12c (from CS-7 and CS-8). In like manner, the stepping switch SS-33 will progress down to its twentieth contact or position, and thus one at a time it will bring into operation and maintain in operation those pickup stations which have been preselected for the run. The last operation of the "start up" stepping switch SS-33 during a run will be to advance to its position or contact 21, which completes a circuit through the latching relay coil K-31-L. This opens contacts K-31a in the circuit of coil SS-33 and that stepping switch can move no further; it opens contacts K-31b so that the power circuit through the wiper of the stepping switch SS-33 is cut off; and it prepares a circuit for the "close down" stepping switch SS-34 by closing contacts K-31c in the circuit of coil SS-34, and by closing contacts K-31d in the supply circuit to the wiper of SS-34. From then on during the run the stepping switches do not operate, and the control circuit functions only with respect to rejects until the time comes to shut down the run automatically.

Referring to FIG. 42, during each revolution of the machine, cams V and VI close switches CS-5 and CS-6 at the time when the odd numbered pickup stations are about to pick up a sheet from the associated bundles. Similarly, cams VII and VIII close switches CS-7 and CS-8 at the time when the even numbered pickup stations should be picking up a sheet. In each case, the switches CS-5 and CS-6, and switches CS-7 and CS-8, operate simultaneously and are connected in parallel to assure completion of a reject circuit. The possible operation of a reject circuit will be explained with reference to the first pickup station, it being understood that the other reject circuits operate in a similar manner.

When switches CS-5 and CS-6 close this supplies power to L-41 if S-35 has closed (FIG. 41D). Then, solenoid L-41 will act to displace that memory pin in wheel 875 which is in front of the solenoid armature. The location of this first station reject solenoid is shown in FIG. 40.

This serves as a memory of the fact that no sheet was transferred to the assembling conveyor at the first station, although there should have been a pickup and a transfer. Therefore, when the displaced pin moves around, due to rotation of the memory wheel in time with the machine, and closes the reject switch S-58 (FIG. 41E), this will complete a circuit to the reject relay K-36. Shortly thereafter, cam X will close switch CS-10 to supply power to this circuit and K-36 will lock itself in through its holding contacts K-36a, and it will close its contacts K-36b in the circuit of the reject solenoid coil L-66. This is the coil of the reject solenoid, such as shown at 690 in FIG. 30, and upon being energized, it will lift the reject shoe as previously described. Also, the normally closed contacts K-36c in the circuit of the guide sheet feeder solenoid circuit, coil L-67, are open for the period of time during which K-36 remained energized. This duration is determined by the cam X of switch CS-10, since as soon as the follower of that switch drops to the low part of the cam, CS-10 will open and terminate power to K-36.

When the machine is set up and started on a run, a counter is preset to a count equal to the total number of packaged patterns desired from that run. Any suitable counter of conventional design can be used, and therefore in the drawings, FIG. 41E, this counter is shown schematically by the dotted outline 920. This counter includes a D.C. relay 922 having its contacts 923 connected into the control circuit of the coil of relay K-32. This relay has normally closed contacts K-32a which were

mentioned previously, in the circuit of the stepping switch coil SS-33. There are also contacts K-32b, normally open, in the circuit of the stepping switch coil SS-34, and a third set of contacts K-32c which are connected across the switches CS-1 and CS-2, in parallel with the circuits containing contacts K-38a.

Cam IX is arranged to close the cam switch CS-9 once for each machine cycle, and this in turn energizes the coil of relay K-35 once each cycle, closing its contacts K-35a and applying power to the full wave rectifier circuit 924 which in turn applies D.C. power to the relay 922. This circuit is normally mounted ineffective by the counter, until the counter has tolled off the count preset into it at the beginning of a run. Then, contacts 923 shift to complete a circuit through K-32 and the contacts K-32a open, and K-32b and K-32c close. From then on the cam switches CS-1 and CS-2, closing alternately, continue to send pulses to the stepping switch coil SS-34, and since the latching relay K-31-L is energized, the first such pulse moving the stepping switch SS-34 to its 1 contact will complete a circuit through the unlatching coil K-38-R to unlatch relay K-38 and open contacts K-38a, and also will complete a circuit through the reset coil K-33 of stepping switch SS-33, resetting it to its home contact.

At the same time, assuming that the first pickup station is in operation, switch S-15 will be closed and a circuit will be completed through the unlatching coil K-11-R, and the latching relay K-11 will be released. This results in opening of contacts K-11a and K-11c and closing of the latch solenoid control contacts K-11b. This shuts down the first pickup station and it will no longer pick up and carry sheets to the assembling conveyor. As stepping switch SS-34 continues to step down to its contact 20, it will pass through the same circuit sequence as set up at the beginning of a run, in other words according to those switches S-15 through S-34 which had been closed, and one by one the active pickup stations will be shut down.

The final pulse to the coil SS-34 will move the stepping switch to its contact 21, and this completes a circuit through the unlatch coil K-31-R, releasing the latching relay K-31 which in turn opens its contacts K-31c and breaks the circuit to the coil SS-34. Also, K-31d open to terminate power to the wiper of SS-34 and K-31b close to apply power to the wiper of SS-33, which is now, however, in its home position, and for future operation contacts K-31a close in the circuit of coil SS-33. The assembling and transfer mechanisms of the machine are thus shut down in sequence so that there is no pickup of a pattern which contains less than the full number of sheets required to make a complete pattern.

Referring again to FIG. 41E, the cams XIX and XX operate switches CS-19 and CS-20, respectively, and these control the supply of power to the valve solenoids L-62a and L-62b. Similarly, cams XXI and XXII control the supply of power of the normally open switches CS-21 and CS-22 and these switches control the energizing of the valve solenoids L-63a and L-63b, respectively. The pair of cams XIX and XX are driven from one end of the shaft 360, as shown in FIG. 22, and the other pair of cams XXI and XXII are driven from the opposite end of that shaft. The solenoids L-62a and L-62b control conventional three-way air supply valves (not shown) which in turn are connected to supply (or exhaust) air under pressure to the opposite sides of the movable folding plow 415. Similarly, the solenoid coils L-63a and L-63b control the same conventional type of valves to supply pressure air to the opposite sides of the pneumatic cylinder 432 controlling the folding plow 430.

Thus, the operation of these moving folding plows is coordinated with the movement of the stream-folding conveyor, and hence with the function of the entire machine. Briefly, when a pattern group approaches the stationary part 410 of a folding plow the cam XIX is arranged to close switch CS-19 and energize L-62a, and thus the

movable plow 415 will swing inwardly toward the center of the stream-folding conveyor as the pattern group passes over it. Shortly thereafter cam XX will close CS-20 to energize the opposite solenoid L-62b to return plow 415 to its normal position. The controls for the movable plow 430 operate in like fashion.

The solenoid L-67 is normally deenergized, and is part of a solenoid valve (not shown) which is connected in the vacuum supply to the tube 705 (FIG. 35) of the guide sheet feeder mechanism. Cam XVI controls normally open switch CS-16 in the circuit of the solenoid valve, and also incorporated in this circuit are the normally closed contacts K-36c, and the normally open contacts K-39a. If there is a reject signal which energizes relay K-36, as previously described, K-36c will thus be opened and will break this circuit to prevent the feeding of a guide sheet at the time when a rejected pattern would otherwise be passing the guide sheet supply mechanism.

When a pattern passes from the tuck-folding mechanism toward the reject station it passes between the belts 588 and 590, and the roller 636 in carriage 635 (FIG. 30) will move in response to the thickness of the passing pattern. This movement is detected by switch S-84 (FIG. 41E) which will be closed by such movement of the roller 636 and will thus complete a circuit energizing relay K-39, which closes its contacts K-39a in the circuit of solenoid L-67 and closes its contacts K-39b which constitute a holding circuit around switch S-84. Thus every time a pattern leaves the tuck-folding mechanism it will set up the circuit for vacuum supply to the guide sheet feeder mechanism, but this circuit can be broken if there is a reject signal which causes relay K-36 to be energized.

Cams XVII, XVIII, XXIII and XXIV are operated from the shaft which rotates the control gear 820 in FIG. 34. These cams are arranged to close the corresponding normally open switches CS-17, CS-18, CS-23 and CS-24 at appropriate times in the cycle of machine operation. Switch CS-17 is in the circuit of the envelope feeder vacuum solenoid L-68, and this solenoid controls a valve which in turn controls the supply of vacuum to the tube 802 shown in FIG. 33. In this circuit there are normally open contacts K-40a of relay K-40, and the coil of this relay is in turn under the control of the normally open switch S-85 which is bypassed by the normally open holding contacts K-40b. Switch S-85 is operated in response to movement of the arm 795 (FIG. 33) when a pattern passes over the roller 798. Thus, passage of a pattern into the packaging station will complete the power supply to the envelope vacuum feed tube.

Switch CS-18 is in the circuit of solenoid L-69, which controls a normally closed valve in the pressure air supply to the air blast nozzle or tube 792 (FIG. 37). This switch is arranged to close prior to arrival of a folded pattern at the packaging station, so that a puff of air will be directed to the envelope at the bottom of the stack, to assure that this envelope is open.

Finally, switches CS-23 and CS-24 control the power supply circuits to a pair of solenoids L-70 and L-71 which in turn control conventional solenoid-operated three-way valves connected to supply or exhaust air from the opposite sides of the pneumatic cylinder 838 (FIGS. 37 and 38). It will be recalled that operation of this air cylinder controls the scissors-like function of the discharge gripper mechanism shown in open position in FIG. 37 and in closed position preparatory to withdrawing an envelope in FIG. 38.

Another feature of the control system can be understood with reference to the switch S-60 in FIG. 41E. This is a switch which bypasses the contacts 923 of the counter relay 922. Switch S-60 is normally open and can be moved to a closed position by the operator if for any reason it is desired to start the shut down sequence of the machine prematurely. For example, if the machine has been set up to run a quantity of five hundred patterns, and for some reason it is desirable to shut down

at the end of one hundred patterns, when the first one hundred patterns have been run, the operator can close switch S-60 and this will energize K-32, in turn opening K-32a and closing K-32b and K-32c whereupon the shut down sequence of the stepping switch SS-34 will commence as previously described. Another safety feature of the control system, which may be incorporated if desired, although it is not a necessary part of the control, involves the parallel connected normally closed safety switches S-92, S-93 and S-94, shown in FIG. 41A, and mounted in series position physically about the periphery of the memory wheel as shown in FIG. 40. If this circuit should be used, then it is connected into the series safety circuit shown in FIG. 41A, and if there are three successive rejects, then there will be three successive memory pins displaced, and when these pins reach the position of these switches all three switches will be opened at one time to break the safety circuit, which in turn will break the holding circuit of relay K-6. This in turn breaks the circuit of relay K-5 and it is deenergized to open the clutch circuit and close the brake circuit.

Summary

From the foregoing description it will be apparent that the present invention provides apparatus whereby sewing patterns or like materials, involving the collecting of relatively lightweight thin sheets of paper or the like, can be assembled, folded, and packaged automatically, and at relatively high speed. The features of the apparatus include provision for setting up for a subsequent run on the supporting saddle bars while the machine is in an automatic regime, and these bars include guide marks or the like, as shown in FIG. 17, whereby the sheets can be placed in predetermined position with respect to the center line of the machine conveyors. The automatic controls provide for a wide degree of flexibility in choice of pickup stations which will operate during any run, and within each pickup station as to the width of the sheet to be accommodated. The machine automatically operates through a starting cycle and a shut down cycle such that at these times no pattern is assembled which does not include a complete collection of the necessary sheets from all the pickup stations to be in operation. If at any time there is a miss in the pickup station in operation, the memory and control circuits record this fact temporarily and reject the resultant defective pattern before it reaches the packaging station, by removing it from the machine.

The control circuits for the machine include provisions to avoid the feeding of an instruction or guide sheet in the event that there is no folded pattern approaching the guide sheet feeder mechanism, and likewise the controls avoid the feeding of empty envelopes into the discharge conveyor.

While the method and form of apparatus herein described constitutes a preferred embodiment of the invention, it is to be understood that the invention is not limited to this precise method and form of apparatus, and that changes may be made therein without departing from the scope of the invention which is defined in the appended claims.

What is claimed is:

1. Apparatus for assembling a plurality of thin sheets of different size and inserting the assembled sheets in a container, comprising a plurality of support members each capable of holding a supply stack of one of the plurality of sheets, said support members being arranged sequentially along an assembly path, at least one assembling carrier mounted for movement along said path and means for driving said carrier along said path, a plurality of pickup devices, one for each support member, operative to remove a single sheet from the corresponding support member and to transfer such sheet onto said carrier for assembling on said carrier a group consisting of one of each of the different sheets on said support members, folding apparatus operative to receive such group of sheets from

said assembling carrier and to fold such group of sheets to predetermined dimensions, an inserting mechanism receiving the folded group of sheets from said folding mechanism, means for supplying containers to said inserting mechanism, and means incorporated in said inserting mechanism for placing the folded group of sheets in a container.

2. Apparatus as defined in claim 1, wherein said means for supplying containers is a hopper having an open bottom and arranged to support a stack of envelopes with the mouths of said envelopes in predetermined relation facing said open bottom, and the means for placing a folded group of sheets in a container comprises means adjacent the bottom of said hopper for engaging edge portions of the lowermost envelope for supporting the same and leaving the mouth of the lowermost envelope free to open, conveyor means arranged with respect to said hopper and to said folding apparatus to receive folded groups of sheets from said folding apparatus and to carry such groups of sheets into the mouth of the lowermost envelope, and means for introducing a stream of air under pressure into the mouth of the lowermost envelope in said hopper for expanding said envelope to receive a folded group of sheets from said conveyor means, and feeder means cooperating with said hopper and operative on the lowermost envelope therein in timed relation to said conveyor means for withdrawing the lowermost envelope from said hopper subsequent to placement of the sheets in said envelope.

3. A machine for assembling and packaging a plurality of different thin printed sheets making up a construction pattern such as for dress making, comprising a plurality of saddle members forming mounts for bundles of the various sheets required to make up a complete pattern, a pickup device associated with each said saddle member and arranged to remove a single sheet from a bundle thereon, an assembly conveyor operative to remove sheets from each of said pickup devices and thereby to group the sheets into complete pattern groups, drive controls for said pickup devices and for said assembly conveyor correlating the operation thereof to cause each said pickup device to present a single sheet from the bundle on its associated saddle member to said assembly conveyor in predetermined timed relation such that said conveyor collects the sheets from the bundles in a predetermined order and carries the complete pattern group to a discharge position, transfer means operatively associated with said conveyor and forming therewith a discharge position where the complete groups are removed from said conveyor, folding apparatus receiving said groups from said transfer means and operating thereon to fold each group to a predetermined size, packaging means receiving the folded groups from said folding apparatus and including a supply of individual packages for each such group, and apparatus incorporated in said packaging means to place each folded pattern group into a package and then to discharge the same from said packaging means.

4. A machine for assembling and packaging a plurality of different thin printed sheets making up a construction pattern such as for dress making, comprising a plurality of saddle members forming mounts for bundles of the various sheets required to make up a complete pattern, a selectively operable pickup device associated with each said saddle member and arranged to remove a single sheet from a bundle thereon, an assembly conveyor to remove sheets from each of the operative said pickup devices and thereby to assemble the sheets into complete pattern groups, drive controls for said pickup devices and for said assembly conveyor correlating the operation thereof to cause each operative said pickup device to present a single sheet from the bundle on its associated saddle member to said assembly conveyor in predetermined timed relation such that said conveyor collects the sheets from the bundles in a predetermined order and carries the complete pattern group to a discharge position, transfer

means operatively associated with said conveyor and forming therewith a discharge position where the complete groups are removed from said conveyor, and controls connected to said pickup devices for placing in operation only those pickup devices at which a bundle is present on the corresponding saddle member to adapt said machine for handling of patterns having different numbers of sheets.

5. A machine for assembling and packing groups of individual thin flexible sheets from separate bundles thereof, comprising pickup means for withdrawing a single sheet from each bundle, means operative in conjunction with said withdrawing means to assemble such single sheets into a group, folding apparatus receiving such groups of sheets and operating on each group to fold it to a predetermined size, means providing a supply of packaging envelopes, loading means receiving the folded groups from said folding apparatus for receiving said envelopes singly in succession operating to place each folded group in an envelope, control means responsive to failure of any one pickup means to remove a sheet from the corresponding bundle, and a reject mechanism operated by said control means to remove an incomplete group from the machine before such group is conveyed to said loading means.

6. Apparatus for assembling a plurality of thin sheets for insertion in a container, comprising a plurality of support members arranged in sequential fashion and each capable of holding a supply bundle of one of the plurality of sheets, an assembling conveyor means mounted for movement along said sequentially arranged support members and including at least one assembling carrier mounted thereon for movement in sequence past each of said support members, drive means for said conveyor means, a plurality of pickup stations equal in number to said support members and arranged in corresponding relation to said support members for transferring a single sheet from the related support member to said assembling carrier, means driving said pickup devices in timed relation to said conveyor means such that each pickup device will present to said assembling carrier a sheet from its associated bundle as said assembling carrier moves past the pickup devices, and control means for each of said pickup devices coordinated with the operation of said conveyor means to cause the individual pickup devices to remove a single sheet from the associated bundle and to transfer the sheet to said assembling carrier.

7. Apparatus as defined in claim 6 wherein said control means includes switch controls corresponding to each of said pickup means and operable to disable selected ones of said pickup means for use of said apparatus in assembling a plurality of sheets less in number than the total number of pickup devices in said machine.

8. Apparatus as defined in claim 6 wherein said control means includes a starting control system and a shutdown control system operative on said pickup devices to cause said pickup devices to be activated in a sequential fashion and to be deactivated in the same sequential fashion while said conveyor means continues to operate such that during starting and stopping of the apparatus only complete groups of sheets are presented to said assembling conveyor.

9. Apparatus as defined in claim 6 wherein said control means includes detectors responsive to the operation of each of said pickup devices and operable to produce an indication of failure of a pickup device to pick up a sheet from its associated bundle and supply such sheet to the assembling carrier, memory mechanism operated in coordinated relation to said apparatus and responsive to functioning of at least one of said detectors to provide a temporary record of such failure of a pickup device, and reject mechanism in said apparatus located to receive all groups of sheets assembled in said apparatus and operative under the control of said memory mechanism to segregate any incomplete group of sheets as indicated by functioning of said detectors.

10. A machine for assembling and packaging a plurality of different thin printed sheets, comprising a plurality of saddle members forming mounts for bundles of the different sheets, a pickup device associated with each said saddle member and arranged to remove a single sheet from a bundle thereon, an assembly conveyor operative to remove sheets from each of said pickup devices and thereby to gather the sheets into groups, drive controls for said pickup devices and for said assembly conveyor correlating the operation thereof to cause each said pickup device to present a single sheet from the bundle on its associated saddle member to said assembly conveyor in predetermined timed relation such that said conveyor collects the sheets from the bundles in a predetermined order and carries complete groups to a discharge position, transfer means operatively associated with said conveyor forming a discharge position where the complete groups are removed from said conveyor, folding apparatus receiving said groups from said transfer means and operating thereon to fold each group, packaging means receiving the folded groups from said folding apparatus and including a supply of individual packages for each such group, and apparatus incorporated in said packaging means to place each folded group into a package.

11. A machine as defined in claim 10 wherein said drive controls include a detector at each pickup device responsive to the operation of the pickup device and operable to produce an indication of failure of the pickup device to pick up a sheet from its associated bundle, memory mechanism operated in coordinated relation to said conveyor and said folding apparatus and responsive to functioning of any one of said detectors to provide a temporary record thereof, and reject mechanism in said apparatus located between said folding apparatus and said packaging means to receive folded groups of sheets, and a control connection from said memory mechanism to said reject mechanism to segregate any incomplete group of sheets from the groups passing to said packaging means.

12. In a machine for assembling a plurality of different thin sheets, the combination of a plurality of saddle members forming mounts for bundles of the various sheets to be assembled, said saddle members being arranged in consecutive fashion, a pickup device associated with each saddle member and arranged to remove single sheets from a bundle thereon, an assembling conveyor including a continuous conveyor mechanism having a plurality of carrier bars thereon in spaced relation, the space between adjacent carrier bars being in excess of the sheet length to be handled, each of said carrier bars having a plurality of barbs thereon arranged to project from the carrier bars toward said pickup devices whereby a sheet presented by any pickup device will be impaled on said barbs, drive means connected to operate said pickup devices and said conveyor in timed relation for causing each said pickup device to present single sheets from the bundle on its associated saddle member for transfer of said sheets onto the assembling conveyor, and means cooperating with said assembling conveyor along the direction of movement thereof beyond said pickup devices to remove assemblies of sheets from the barbs.

13. In a machine as defined in claim 12, the combination including controls for said pickup devices for selective operation thereof to cause certain ones only of said pickup devices to present sheets to said assembling conveyor.

14. In a machine for feeding single sheets from a bundle thereof, the combination of a saddle member forming a support over which a bundle of sheets is draped to hold a portion of the sheets between the leading and trailing edges thereof substantially above such edges, a pickup device including a continuously rotatable member mounted to rotate on a fixed axis parallel to and above said saddle member, pickup finger members mounted for reciprocating movement on said rotatable member toward and away from the uppermost sheet on a bundle carried

on said saddle member, means normally and yieldably urging said pickup members to their fullest extension from said continuously rotatable member to accommodate movement of the ends of said pickup members against the uppermost sheet in the bundle as the thickness of the bundle decreases with removal of sheets therefrom, and means for actuating said pickup members against the top of a bundle to engage the uppermost portion of the top sheet on the bundle between its edges to remove a single sheet from the top of a pile on said saddle member and simultaneously to form a fold in the removed sheet adjacent the portion of the sheet engaged by said pickup members.

15. Apparatus as defined in claim 14 wherein said rotatable member is driven with predetermined angular acceleration and deceleration motion, and mechanism correlated to the motion of said rotatable member for causing said pickup members to move toward the bundle during a decelerating movement of the rotatable member and to carry a sheet from said bundle outward away from the next sheet on the bundle during an accelerating movement of said rotatable member.

16. Apparatus as defined in claim 14, wherein controls are provided for said actuating means for disabling the operation thereof to stop the feeding action.

17. In a machine for assembling and packaging a plurality of different thin printed sheets and the like, the combination of an assembling conveyor, a plurality of saddle members forming mounts for bundles of the various sheets making up a complete assembly, each said saddle member comprising at least one upright member and a transversely 25

20
15
30

a support bar over which a bundle of sheets can be draped, said saddle members being spaced apart beneath the length of said conveyor, a pickup device mounted between each said saddle member and the portion of the conveyor thereabove and arranged to remove single sheets from a bundle supported thereon and transfer the sheets from the bundle to the conveyor, and guide means on said support bar forming a reference to the location of said pickup device for aligning a bundle of sheets on the saddle member in predetermined relation to said pickup device.

18. Apparatus as defined in claim 17 in which said saddle member is approximately twice as great in width as said pickup device and wherein said guide means are formed as separate groups of reference marks spaced along said support bar, and a movable mount for said saddle member providing for shifting thereof in parallel relation to said pickup device for bringing either of said sets of reference marks into operate position with respect to said pickup device.
